UNITED STATES PATENT OFFICE.

ROBERT W. McLEAN, OF BRIDGEWATER, MASSACHUSETTS, ASSIGNOR TO CARVER COTTON GIN COMPANY, OF EAST BRIDGEWATER, MASSACHUSETTS, A CORPORATION OF MASSACHUSETTS.

LINTER GIN.

Application filed August 2, 1924. Serial No. 729,725.

This invention pertains to that general class of machines adapted to remove useful fibres from their attachments, such for example, as gins, cotton seed linters or linter gins, wool burring machines, and the like, and has particular reference to saw gins for de-linting cotton seed, although unrestricted except in minor details to this specific type of machine.

10 Objects of the invention are to provide an individual condenser gin of the above type so designed as substantially to avoid the delivery of dust or lint laden air to the workroom; to provide a gin which will be comparatively quiet in operation; to provide a closed circuit gin having air passages of such form as to avoid the production of eddy currents at undesired points; and to provide a gin which requires less power for operation than gins of usual character.

Further objects are to provide for the better separation of the various products of the gin, including the seeds, clean fibre, mottes, and short dirty fibre; to provide a gin of compact design which occupies a minimum floor space and which may be closely associated with like gins or other machines; and to provide a drive unit for such a machine capable of driving the operative parts of a single gin or two adjacent gins, as may be desired, and permitting the gin or gins to be stopped and started without difficulty.

35 Further objects are to provide for ready adjustment of the various operative elements of the gin to suit varying conditions and to secure maximum efficiency, as well as for accessibility of parts to permit their adjustment, removal, or repair; to permit observation of the enclosed working parts during operation; and in general to improve and simplify the usual structural and operative elements of such a machine.

40 In the accompanying drawings, a preferred embodiment of the invention is illustrated, and in such drawings:—

Fig. 1 is a front elevation of a linter gin embodying the present invention, including the driving unit;

60 Fig. 40 is a fragmentary vertical section to large scale substantially on the line 40—40 of Fig. 3;

65 Fig. 41 is a horizontal section on line 41—41 of Fig. 40; and

Fig. 42 is a fragmentary vertical section illustrating a modified and preferred form of back for the breast structure.

In that embodiment of the invention herein selected for illustration the novel 70 mechanical features are shown as applied to a saw gin of the type employed for de-linting cotton seed and hereinafter referred to and claimed as a "linter gin," although many of such novel features are of broad 75 utility and capable of embodiment in gins or other fibre treating machines of different types, and it is to be understood that as herein employed the term "linter gin" is used merely for convenience in description 80 and not in a limiting sense.

General construction.

In the preferred arrangement herein illustrated the gin structure comprises a main 85 or front unit having spaced end frames 1 and 2 preferably in the form of castings providing solid end walls. These end frames support a substantially horizontal floor 3, (Fig. 7) a top or cover 4 which is preferably 90 of sheet metal, and a front wall 5 which inclines upwardly from the floor 3 and is then continued vertically for a short distance terminating at the point 6.

This front unit preferably contains the 95 usual feed box or hopper with its feed roll for advancing the material, for example cotton seed, to be treated, and the feed regulating means, for example a feeler or detector which controls the rate of feed, and which in 100 turn is controlled by the amount of material delivered by the feeding means.

The front unit also comprises a breast structure embodying a roll box having a float roll therein; a grate-fall and rake head; the 105 instrumentality employed for removing the fibre from its attachments, for example a saw cylinder; the means for doffing the fibre from such detaching means, for example a rotary brush which may also constitute 110 means for setting up a fibre conveying air current within the casing of the machine; and means for separating the motes and trash from the fibre suspended in the air current.

115 The rear unit of the structure comprises end frame members 9 and 10 (Fig. 2) which are bolted to flanges 7 and 8 respectively (Figs. 3 and 4) of the main frame members 1 and 2. This rear unit is furnished with a floor 11 (Fig. 8), a cover 12, the latter 120 preferably being of sheet material, for example sheet metal, and a rear wall 13. The floor 11 is spaced vertically from the floor 3 of the main or front casing, being supported 125 at its forward edge by means of a bar 14 secured at its ends to the main frame members 1 and 2. The space below the bar 14 is normally closed by means of a hinged door 130 15 which may be raised to permit inspection

and cleaning of the bottom of the main casting. The lower part 13 of the rear wall 13 of the rear unit is likewise hinged to provide access to the lower part of the rear unit.

5 This rear unit preferably comprises means for separating dust from the air currents, the term dust being here employed as comprising small particles of sand, grit and other materials such as are not commonly removed by the usual moting means, as well as extremely short pieces of fibre which ordinarily appear as fly in the work room and which while having some commercial value is not readily removed from the air current by the usual condensing means.

10 The rear unit also preferably comprises a settling chamber cooperating with a condenser, for example a rotary cylindrical screen upon whose outer surface the clean long fibres are deposited; a doffer roll for removing the fibres from the surface of the condenser in the form of a continuous bat; a presser roll for compacting the bat as it passes over the doffer roll; a lap roll for receiving and guiding the bat as the latter is delivered by the doffer roll; and a bat roll upon which the bat is wound.

15 The front and rear units also contain suitable partitions, deflectors, and regulating means for determining the flow of the air current in passing from one of the operative instrumentalities to another.

20 While the above arrangement of the operative instrumentalities in certain groups within the front and rear units of the machine is desirable it is to be understood that the invention is not in any manner restricted to such a grouping of the operative instrumentalities but that they may be grouped in a different manner if desired, while the distinction herein made between the front and rear unit is merely for convenience both in construction and description and is not in any manner necessary to the proper functioning of the machine as a whole.

Feeding means.

25 The selected embodiment of means here- in illustrated for feeding the material, for example cotton seed, to the operative instrumentalities comprises a feed box or hopper 21 (Fig. 7) having end frame members 16 and 17 (Fig. 2) which are mounted upon the upper edges of the frame members 1 and 2 respectively. These end members 16 and 17 support a vertical rear wall 18 (Fig. 7) and a front wall preferably comprising a rearwardly and downwardly inclined upper part 19 and a vertical portion 20.

30 A shaft 22 is journalled in the end members 16 and 17 respectively and carries a feed roll 23 of any desired construction. A sliding gate 24 of usual type may be provided for cooperation with the feed roll 23

in regulating the amount of material fed downwardly by the latter. This gate 24 is provided with toothed racks 25 on its rear face engaging pinions 26 mounted upon a shaft 27 journalled in suitable brackets carried by the end members 16 and 17. This shaft may be turned by means for example of a lever 27^a provided with a locking segment 27^b (Fig. 10), having openings for the reception of a locking pin 27^c.

35 A drive shaft 28 is mounted in brackets upon the rear wall 18 of the feed box and is provided at one end, preferably the right-hand end of the machine as herein illustrated, with a pulley 29 (Fig. 4) which is rotated by means of a driving belt 30.

40 The opposite end of the shaft 28 is furnished with a crank disc 31 (Fig. 3) provided with a crank pin 32 connected to one end of a link 33 whose opposite end is pivotally secured to a rocking segment 34 turning freely upon the end of the feed roll shaft 22. The segment 34 supports a pawl 35 (Figs. 3 and 9) adapted to cooperate with the teeth of a ratchet wheel 36 secured to the shaft 22 so that upon rotation of the shaft 28, the ratchet wheel 36, shaft 22, and feed roll 23 are intermittently turned.

45 The engagement of the pawl 35 with the teeth of the ratchet 36 is determined by means of a movable guard sector 37 turning freely upon the shaft 22 and having an arcuate shield 38 which overlies the edge of the wheel 36. Preferably the sector 37 is furnished with a counterweight 39 so that it may readily be moved to any desired position. The sector 37 is furnished with a pin 40 (Fig. 9) engaging a slot 41 in one end of a connecting rod 42 of adjustable length whose other end is pivotally secured to a regulating lever 43 hereinafter more fully described.

50 From the lower part of the rear wall 18 of the feed box a partition 44 slopes downwardly and forwardly. A support 45, normally forming a continuation of the upper surface of the partition 44 is hinged to the lower edge of the latter. The support 45 is furnished with a longitudinal slot for the reception of one or more steel bars 46 which are suitably magnetized during the operation of the machine and which act to separate particles of iron or steel accidentally included with the material being treated.

55 A plate 47, preferably of sheet metal, extends downwardly and forwardly from the lower edge of the support 45. This plate is furnished with end flanges 48 for attachment to the end members 16 and 17 of the feed frame.

60 A transverse bar 49 projects downwardly and forwardly from the lower edge of the front member 20 of the hopper and a cover 130

50 is hinged to its lower edge. This cover is preferably of sheet metal supported upon end castings 50^a and 50^b respectively, (Figs. 9 and 10) and may be swung upwardly and 5 retained in open position by means of a spring latch 51 thus permitting inspection of the stream of material flowing down over the plate 47.

Breast structure.

10 The breast structure herein illustrated as embodying a preferred form of the invention comprises a back 52 (Fig. 7) desirably constructed as a metal casting and having 15 a concave forward surface constituting a portion of the rear wall of a roll box 52^a hereinafter more fully described.

Brackets 54 and 55 (Figs. 7 and 9) are secured to the rear side of the back 52. These 20 brackets are furnished with journal openings for a supporting shaft 56 whose opposite ends are flattened vertically and received in vertical guideway 56^a in the frame members 1 and 2, respectively. The 25 ends of the shaft are furnished with vertical, threaded openings for adjusting screws 56^b by means of which the position of the shaft and the breast structure supported thereon may be adjusted vertically.

30 The brackets 54 and 55 are provided with rearwardly extending socket members 58 and 59 respectively for the reception of rearwardly extending rods 60 and 61. These rods support a bar 62 at their outer ends 35 which constitutes a support for removable counterbalance weights 63. A sufficient number of these weights is mounted upon the bar 62 substantially to counterbalance the weight of the entire breast structure.

40 The back 52 is preferably provided with a rearwardly extending flange or lip 64 (Fig. 7) which contacts with a flexible flap or 45 sealing member 65 secured to the forward edge of the cover 4. This flap being flexible and preferably resilient, contacts with the lip 64 in all positions of the breast structure so that leakage of air between the breast structure and the cover 4 is prevented.

The breast structure also comprises end 50 plates 66 and 67 (Figs. 7 and 4) which are rigidly secured to the opposite ends respectively of the back 52. These end plates are provided with notches 66^a and 67^a in their forward edges. Flanged end frames 66^b and 55 67^b are disposed at the inner sides of the plates 66 and 67 respectively and are provided with bearing pins 66^c and 67^c pivotal- 60 ly engaging the notches 66^a and 67^a respectively. The end frames 66^b and 67^b are connected at their upper ends by an elongate bar 68 whose upper edge supports the cover 50. Preferably resilient material such as a 65 felt strip 68^a is interposed between the bar 68 and the cover 50 to prevent leakage of air therebetween.

A forwardly convex breast board 69, preferably of sheet metal curves forwardly from the lower edge of the bar 68 and then downwardly to the point 70. This breast board constitutes the front wall of the substantially cylindrical roll box 52^a. Releasable bolts or latches 69^a and 69^b respectively are preferably secured to the lower part of the breast board 69, such latches or bolts cooperating with complementary members or openings in 75 the plates 66 and 67 respectively to retain the breast board in normal position.

The upper part of the back 52 is furnished with an elongate bearing 71 for a shaft 72 which supports a feeler or detector plate 80 73. This detector plate is preferably curved to substantially the same curvature as the inner surface of the back 53, normally forming a continuation of the latter.

The shaft 72 is journalled at its opposite 85 ends in the end members 66 and 67 respectively and projects outwardly from the member 66. A collar 74 (Figs. 18 and 19) provided with an arm 75 is secured by means of a key to the projecting end of the shaft 72. 90 The arm 75 terminates in an elongate boss 76 having a bore or opening whose axis is substantially radial to the shaft 72.

The collar 74 is provided with an integral bushing 77 which extends axially of the 95 shaft 72 and upon which a sleeve 78 is mounted which supports and preferably forms an integral part of the regulating arm 43. The arm 43 is preferably furnished with a slot 79 in which the lower end of the 100 connecting rod 42 above described is pivoted. The sleeve 78 is free to turn to a limited extent upon the bushing 77, being secured thereto by means of a set-screw 81 which engages an arcuate slot 80 in the bushing 76. The arm 43 is furnished with a weight 82 at its outer end and with a lateral boss 83 near its inner end. This boss is furnished with an arcuate edge provided with segmentally arranged rack teeth 84 110 cooperating with a pin 85 disposed in the bore in the boss 76. This pin is provided with a head 86 for retracting it from the teeth 84 but is normally projected forwardly into engagement with such teeth by means of a suitable spring. By retracting the pin 85 the position of the regulating arm 43 may vary relatively to the arm 75, thus varying its resistance to movement by the detector 73. 115

Float roll.

A float roll 87 is arranged to turn within the roll box 52^a. A preferred type of float roll herein selected for illustration comprises a pair of angle bars (Figs. 15, 16 and 17) 125 having flanges 88 and 89, and 90 and 91 respectively. These angle bars are disposed in back to back relation with their flanges 88 and 91 overlapping and extending in opposite directions and with their flanges 88 130

and 90 extending oppositely and lying in spaced parallel planes. Thus disposed, the angle bars are securely attached to each other by means of rivets 90.

5 The float roll 87 is provided at its opposite ends with aligned shaft sections 92 and 93 respectively which are mounted to turn in anti-friction bearings in casings 94 and 95 (Fig. 1) respectively supported upon the

10 end frames 66 and 67. While it is preferred to mount the float roll shaft in anti-friction bearings it is of course obvious that bearing of other types may be employed if desired.

The float roll proper comprising the attached angle bars is detachably secured to its shaft sections so that it may readily be removed from the roll box. For this purpose the engaging flanges 89 and 91 of the angle bars are slotted at their opposite ends

20 as indicated at 96, the slots extending inwardly to a suitable distance from the ends, and being of a width substantially equal to the distance between the opposed faces 99 and 100 respectively of the flanges 88 and 90.

25 Each of the shaft sections 92 and 93 is furnished at its inner end with a flattened portion 97 preferably substantially rectangular in section and which is adapted to fit snugly in one of the slots 96 between the opposed surfaces of the flanges 88 and 90 respectively. The members 97 are detachably secured to the float roll by means of bolts 101, 102, 103, and 104 which enter

30 openings in the flanges 88 and 90 respectively. By removing these bolts the float roll may be slipped off from the members 97 and thus withdrawn forwardly from the roll box, the breast board having first been unlatched and swung upwardly to inoperative 40 position about its pivotal supports 66^c and 67^c.

Grate-fall.

45 A preferred type of grate-fall selected for purposes of illustration and by way of example of the various types of grate-fall which may be employed comprises the following structural features.

The back 52 of the breast structure is provided with a rearward offset portion 105 (Figs. 7 and 22) at its lower edge providing a recess 106. A spacer bar 107 is secured by means of bolts 108 to the lower edge of the back 52. This bar 107 is provided with ribs upon its forward face defining spaced recesses or slots for the reception of the upper ends of a series of bars 109 constituting the essential elements of the grate-fall structure. Each of these bars is preferably furnished with a beveled upper end 110 which cooperates with a wedge or clamping bar 112 disposed within the recess 106 and secured in position by means of bolts 113.

55 The bars 109 are of suitable width and cross section, preferably substantially rec-

tangular, and formed of steel which may be heat treated to secure the desired degree of hardness. Preferably these bars are concavely curved at their upper portions 114, (Fig. 23), becoming substantially straight 70 at their lower portions 115.

The lower ends of the bars 109 rest against an abutment number 116 which is supported upon the upper flange of an angle bar 117 secured at its opposite ends to the frame 75 members 66 and 67 and which constitutes the lower member of the grate-fall structure. The bars 109 are held in properly spaced relation upon the rail 117 by means of a clamping plate 118 (Fig. 24) which is secured to the rail by means of bolts 119 and which has spaced ribs 120 on its under surface defining recesses for the reception of the ends of the grate-bars.

80 As thus constructed the bars of the grate-fall are removable individually so that if a bar is bent or broken it may readily be replaced without disturbing the other bars of the series. This arrangement also permits the employment of hardened steel bars 90 which are capable of withstanding much greater wear than is the case with grate-fall bars as usually constructed and while the individual bars are readily movable they are very securely held against accidental displacement by means of the wedge bar 112.

Rake head.

The breast board is stiffened vertically by means of a ribbed center frame 121 (Fig. 100 1) and is stiffened longitudinally by means of a channel bar 122 (Figs. 1, 7 and 21) which is secured to the end frames 66^b and 67^b and also to the central frame 121.

Brackets 123 and 124 are secured to the 105 front face of the channel bar 122 and these brackets provide bearings for a shaft 125 which is also journaled in a bearing 126 carried by the center frame 121 and which is provided with a hand wheel 127 or other 110 suitable device whereby it may be rotated.

115 Each of the brackets 123 and 124 is constructed to provide a housing in which a gear wheel 127 (Fig. 21) is arranged. Each gear wheel 127 is fixedly secured to the shaft 125 and meshes with teeth 128 upon the peripheral surface of a nut 129 mounted in a recess in the corresponding bracket so that while free to turn it is prevented from moving axially. Each of the nuts 129 has a threaded bore engaging the screw-threaded upper end of a rod 130 whose lower end is pivotally connected at 131 to an angle bar 132 extending longitudinally of the breast structure and disposed just in front 120 of the lower end of the breast board 69. The angle bar 132 constitutes the supporting element of the rake head proper which comprises an elongate bar 133 secured to the member 132 and having downwardly ex- 130

tending spaced teeth 133^a which lie respectively in the vertical planes of the grate-fall bars 109.

With the arrangement just described rotation of the shaft 125 causes the bars 130 simultaneously to move upwardly or downwardly thus adjusting the rake head toward or from the grate-fall.

The front surface of the channel bar 122 is continued downwardly by means of a cover plate 135, preferably of sheet metal, secured at its lower edge to a rail 134 extending longitudinally of the breast structure and attached at its opposite ends to the end frames 66^b and 67^b respectively of the breast board.

A cover plate 136 extends between the grate-fall bar 133 and the rail 134, being secured to such members by means of hinges 137 and 138 respectively. The cover 136 thus closes the space between the rail 134 and the grate-fall regardless of the position of the latter, the desired adjustment of the grate-fall being permitted by the flexibility of the lower part of the breast board 69.

Seed board.

A seed guide casing 139 (Figs. 7 and 21), preferably formed of sheet metal, extends downwardly from the member 134. This seed guide casing comprises end members 139^a and 139^b (Figs. 3 and 4) having hooks 140 and 141 respectively at their upper ends which are detachably engageable with pins 142 and 143 respectively projecting outwardly from the end frame members 66 and 67 of the breast structure. The upper edge of the casing 139 overlaps the horizontal flange of the rail 134 when in operative position thus forming a tight joint, but the entire casing may be removed if desired by detaching its hooks from the supporting pins.

The seed guide casing preferably terminates at a point 144 (Fig. 7) substantially in the horizontal plane of the upper edge 6 of the front wall of the machine casing. The space between the upper edge 6 and the periphery of the saw cylinder, hereinafter described, is preferably substantially closed by means of a seed board which extends upwardly and rearwardly. Preferably this seed board comprises a wooden back 145 and is furnished with a sheet metal front member 146 which diverges from the lower edge of the back 145 in an upward direction, extending to a point closely adjacent to the lower edge of the rail 117. The upper edge of the member 146 is connected to the upper edge of the member 145 by means of an arcuate flange 147 following closely the periphery of the saw cylinder.

Breast lifting means.

65 In accordance with the present invention

provision is made for raising the breast structure from its operative position in two stages. A preferred lifting mechanism selected for purposes of illustration comprises a shaft 148 (Fig. 4) journalled in a boss 149 (Fig. 1) projecting from the end frame 2, said shaft being provided at its outer end with a bracket comprising a socket member 150, in which a handle lever 151 is secured.

The shaft 148 projects inside the frame 75 member 2 and is there furnished with a short arm 152 (Figs. 20, 33 and 34) which is forked at its extremity and provided with a pivot pin 153 upon which a roller 154 is mounted to turn freely. This roller is preferably provided with a circumferential groove and is disposed in the vertical plane of the rod 61 which supports one end of the counterweight supporting bar 62.

The side frame 1 is likewise provided with 85 a bearing in which a shaft 164 (Fig. 3) is journalled. The axis of this shaft is somewhat nearer to the axis of the shaft 56 than is the shaft 148, as indicated in Fig. 20. The shaft 164 is provided with a socket 165 in 90 which a handle lever 166 is secured. Just inside the frame the shaft 164 is provided with a short arm 167 (Figs. 7, 9 and 20) carrying a roller 168 which is disposed in the vertical plane of the weight supporting rod 95 60.

As the arms 152 and 167 are disposed just inside the frame members 1 and 2 respectively, the end portions of the magnet bars 46 are cut away or beveled as indicated 100 at 169 (Fig. 34) to permit the desired movement of the arms. The arm 152 is provided with a tail portion 170 (Fig. 33) which is adapted to contact with the underside of 105 the member 44 to limit the swing of the arm. A stop pin 171 is secured to the frame member 1 at the outer side of the latter to limit the downward movement of the lever 166.

As indicated in Fig. 20 the levers 151 and 110 166 are normally in upper position when the breast structure is operatively arranged. If it be desired to raise the breast structure slightly, as for example temporarily to stop the feed of material to the saw cylinder, the handle lever 151 is swung downwardly until the tail 170 stops its further movement. The downward movement of the handle causes the roller 154 to engage the arm 61 and to move the latter downwardly to the position indicated at X (Fig. 20), thus raising the breast structure part way. Before the arm 151 is stopped, the arm 152 passes the vertical plane of the center of the shaft 148 so that the parts remain locked in this position 115 by the weight of the breast structure. To restore the breast structure to nominal position, it is merely necessary to push the arm 151 upwardly.

If on the other hand, it be desired to raise 120 the breast structure to its uppermost posi-

tion, as for example, to expose the saw cylinder for removal, the arm 166 is next swung downwardly to its lower limit, the engagement of the roller 168 with the weight carrying arm 60 swinging the latter down substantially to the position indicated at Y in Fig. 20. In so moving, the roller 168 passes the vertical plane of the axis of the shaft 164 and the breast structure is thus locked by its own weight in this uppermost position and can only be restored to normal position by pushing the handles 151 and 166 upwardly.

15 *Saw cylinder supporting means.*

The preferred embodiment of means for supporting the saw cylinder as herein illustrated comprises a pair of brackets S (Figs. 1, 3, 4, and 9) pivoted to turn about a common axis near the front of the machine frame at its lower part. The upper part of each bracket is of sector shape, and is provided with an arcuate slot 172 whose upper wall is furnished with a curved rack 173. A shaft 174 is journalled in the frame members 1 and 2 and extends through the slots 172 in the two brackets S. This shaft is provided with pinions 174^a which mesh with the respective racks 173. The shaft 174 projects outwardly at one side of the frame, being here illustrated as projecting at the left side, and is provided with a hand wheel 175 by means of which it may be turned. Turning the hand wheel rotates the shaft 174 and causes the brackets S to swing simultaneously in a front to rear direction.

Each bracket S is provided at its upper end with a seat member 174^b for the reception of a bearing cradle 174^c which is detachably secured to its seat in any suitable manner. The cradles 174^c are furnished with bearings 176, preferably of anti-friction type, in which the shaft 177 of the saw cylinder is mounted.

45 The saw cylinder, herein illustratively exemplifying any suitable means for removing useful fibres from their attachments, comprises a series of circular saws 178 secured to the shaft 177 in any desired and usual manner.

50 The end frames 1 and 2 are furnished with suitable recesses 177^a (Fig. 39) for the reception of the bearings 176 when the latter are in operative position. One end of the saw shaft 177 projects beyond its bearing and is furnished with a clutch element hereinafter described. In order to make a close joint between the upper parts of the bearings 176 and the end members 66 and 67 of the breast structure such end members are furnished with vertically adjustable plates 178^a (Fig. 9) having elongate slots 179 to receive screws by means of which the plates are secured to the end members. Thus as 55 the breast structure is adjusted vertically,

the plates may be adjusted relatively thereto to maintain a tight fit with surface of the bearings.

70 *Saw doffing means.*

The preferred form of doffing means herein chosen for illustration comprises a rotating cylindrical brush. For supporting this brush in operative position the end frames 1 and 2 of the machine are furnished with substantially horizontal ledges 180 (Fig. 3) adjacent to the bottoms of the recesses 177^a upon which bearing cradles 181 may be detachably secured in any desired manner. The bearing cradles 181 are provided with suitable bearings preferably of anti-friction type in which the brush shaft 183 is journalled.

This shaft with its bearings may thus be removed forwardly as a unit from the machine frame. Normally the recesses 177^a are closed by removable plates 184 (Fig. 3) which fit snugly against the surfaces of the bearings of the shaft 183 and also against the rear parts of the bearings 176 of the 90 saw cylinder shaft.

95 One end of the shaft 183 is provided with a pulley 185 for a purpose hereinafter described while its opposite end is provided with a clutch element similar in all particulars to the clutch element carried by the saw shaft 177. These clutch elements, together with the means for driving the brush shaft and the saw cylinder shaft in opposite directions will hereinafter be fully described.

100 The brush cylinder or drum B herein illustrated by way of example, preferably comprises spaced end headers 187 and 188 (Figs. 25 and 26) fixedly secured to the shaft 183 and one or more intermediate headers 189. The end headers 187 and 188 comprise imperforate webs or radial flanges 187^a and 188^a respectively and the several headers are provided with peripheral rims 110 190, 191 and 192 respectively. These rims are furnished with circumferentially extending grooves 193 and are embraced by a cylindrical shell 194, preferably of sheet metal, which fits snugly about the rims. A 115 close joint is provided between the shell and rims by pressing or beading the metal of the shell inwardly into the grooves 193 as indicated at 193^a.

120 A series of longitudinally extending circumferentially spaced lags or bars 194, preferably of wood, is secured to the outer surface of the drum by means of screws 196 engaging threaded openings in the rims of the several headers. The lags or bars 194 act 125 as clamps securely to hold brush strips or tufts of bristles 197 between them. By removing one or more of the bars 194, the bristles adjacent thereto may be replaced without necessitating complete disassem- 130

bling of the cylinder. As the heads and peripheral surface of the drum are imperforate there is little tendency of the rotating drum to set up undesired eddy currents, while the resistance to rotation of the drum is slight. The drum is much lighter than a solidly constructed drum and is dust proof.

Division board.

10/ A division board 198 (Figs. 7, 31 and 32) depends vertically into the angular space between the upper peripheral portions of the saw cylinder and brush cylinder. This 15 division board is supported at its opposite ends upon brackets 199 which slide upon ledges 200 upon the inner surfaces of the end frames 1 and 2 respectively. Bolts 201 project outwardly from the brackets 199 20 through elongate slots 202 (Figs. 3 and 31) in the respective end frames. These bolts engage openings in the ends of link bars 203 having screw-threaded extremities which pass freely through openings in bosses 205 25 projecting from the respective end frames. Locking and adjusting nuts 206 engage the threaded end portions 204 of the links 203, thus permitting the division board 198 to be 30 adjusted with accuracy and securely held in adjusted position.

The lower edge of the division board is beveled as indicated at 207 and projects down into close proximity to the line of osculation of the saw cylinder and brush. 35 A resilient flap 208, preferably of sheet metal, projects upwardly and forwardly from the lower part of the division board into engagement with the lower part of the back 52 of the breast structure. This resilient flap securely closes the joint between the division board and the breast structure regardless of the position of adjustment of the latter.

Moting instrumentalities.

45 The space designated M (Fig. 7) which lies substantially below the line of osculation of the saw cylinder and brush constitutes a moting chamber. The lower wall or 50 floor of this chamber consists of a trough-like partition 210 whose forward wall extends upwardly and rests upon the transversely extending shaft 174 at a point below and somewhat forward of the axis of the saw 55 cylinder. The rear wall of the trough structure extends upwardly to a horizontal rail 212 arranged below the rear part of the brush. The member 212 is secured to the end frame members 1 and 2 respectively 60 and the lateral edges of the member 210 are secured by means of flanges 213 to such end frame members.

A conveyor device 214, preferably comprising an endless screw, is disposed in the 65 bottom of the trough structure 210. The

conveyor screw is mounted upon a shaft 215 journaled at one end in a bearing in end frame member 2 and at its opposite end in a bearing carried by a bracket 217 (Fig. 3) secured to the other end frame 70 1. The latter frame is provided with an opening through which the shaft 215 and the end of the conveyor 214 extend. This opening is enclosed by means of a projecting hood or housing 218 normally closed by 75 means of a movable cover 219. The opposite end of the shaft is provided with a pulley 216 (Fig. 4) driven by means of a belt as will hereinafter be described.

The conveyor 214 moves the motes, trash, etc. which collects in the trough 210 longitudinally into the hood 218 and when sufficient material has accumulated therein it lifts the cover 219 and escapes. The escaping material effectually prevents entrance of 80 air beneath the lifted cover and when the mass has been pushed out the cover drops, again sealing the opening. Conveniently, and particularly if a series of machines are arranged in a row, a transversely extending 85 conveyor, of any desired type, not shown, may be arranged to receive the material discharged from the mote delivery hoods of the several machines and carry it to a bin or receptacle which may be located outside 90 95 the work room.

Draft shield.

A preferred form of draft shield, is indicated at 223 (Figs. 7, 36 and 37). This draft 100 shield comprises end frames each of which comprises a downwardly projecting leg 224 and a forwardly inclined diverging leg 225. A piece of sheet material is secured to the rear surfaces of the legs 224 to form the 105 rear member 227 of the shield. This sheet material extends upwardly beyond the tops of the end frames, being then bent to form an acute angle and extending forwardly 110 and downwardly to provide the rear member 229 of the shield, which is secured to the legs 225. That portion of the member 227 which is adjacent to the moting space M is preferably corrugated with transversely extending ribs 228 and its lower part is 115 concaved rearwardly as shown at 226, the concavity of this portion of the draft shield being opposed to that of the flange 221.

The end frames 224 are arranged to leave 120 spaces between them and the inner surfaces of the main frame members 1 and 2 respectively and the sheet material forming the front and rear members 227 and 229 of the shield overlap these spaces. The upper angle of the sheet material is reinforced by 125 means of a second piece of sheet material 230 similarly bent and which is secured to the parts 227 and 229 in any suitable manner.

The draft shield thus constructed is pref- 130

erably supported for adjustment both to vary the moting action in accordance with conditions of use and also to compensate for variations in diameter of the saw cylinder.

One desirable means for so supporting the draft shield is exemplified in the construction illustrated. In accordance with this preferred construction a pair of spaced 10 guide flanges 231 and 232 (Fig. 37) is provided upon the outer surface of each of the end frames 1 and 2 respectively. Each pair of guide flanges furnishes a guideway in which a plate 233 may slide. Each plate 15 is provided with a screw-threaded rod 234 projecting from its end and passing freely through an opening in a boss 235 projecting from the corresponding end frame. Each 20 rod is furnished with adjusting and locking nuts 236 by means of which its plate may be adjusted and securely held in the desired position.

The plates 233 are furnished with aligned 25 bearings for the opposite ends of a shaft 237 which extends transversely across the machine. At one end this shaft is provided with an arm 238 having a segmental portion 239 provided with an arcuate slot 240 for the reception of a locking screw 242 30 engaging a threaded opening in the adjacent plate 233. The outer end of the arm 238 is furnished with an acuating handle 241.

The shaft 237 is provided with arms 243 just inside each of the frame members 1 and 15 2 respectively. Each of these arms is pivotally connected to the lower end of a fulcrum link 244 which extends upwardly adjacent to the inside of the frame member. These links are furnished with elongate 0 slots 245 for the reception of guide pins 246 projecting inwardly from the respective plates 233. The end frames 1 and 2 are furnished with elongate slots 237^a and 247 5 for the passage of the shaft 237 and the pins 246 respectively, thus permitting free adjustment of the plate 233.

The upper end of each of the fulcrum links 244 is beveled to provide a knife edge at 248 which enters the angle between the members 227 and 229 of the draft shield which is thus supported to swing freely from its upper edge.

Links 249 (Fig. 7) are secured to the lower ends of the legs 224 of the respective end frames of the draft shield and extending forwardly are connected to arms 250 fixed to a transverse shaft 251 journaled in the end frames of the machine. This shaft is provided with a sector arm 252 at one end, (Fig. 3) such arm being disposed outside the frame and being provided with an arcuate slot for the reception of a retaining set screw 253.

By adjustment of the arm 252 the lower

edge of the draft shield may be swung to- 65 ward and from the adjacent wall of the trough 210 thus varying the width of the passage 254 between such wall and the draft shield. This movement does not substantially affect the position of the upper end 70 of the draft shield but if desired the entire draft shield structure may be shifted bodily either in a substantially vertical direction by actuation of the arm 238, after loosening the locking screw 242, or in an inclined 75 front to rear direction by adjustment of the nuts 236. Thus as the diameter of the saw cylinder varies the draft shield may be adjusted to compensate therefor and to maintain its upper edge in a position very closely 80 adjacent to the peripheral surface of the saw cylinder.

A substantially horizontal adjustable mote board is disposed in a plane somewhat above the plate 220. A preferred 85 construction of mote board comprises a core 255 of wood and a sheet metal cover which protects the upper surface of the board and which projects downwardly at the forward edge of the core to form a flange 256 whose 90 lower edge is bent upwardly on a curve 257 to engage the under surface of the core. This mote board is mounted to slide in horizontal guides provided upon the inner surfaces of the end frames 1 and 2 and is furnished with spaced racks 258 engaging pinions 259 carried by an adjusting shaft 260. The shaft 260 is journaled in the end frames 1 and 2 and is provided with a hand wheel 261 (Fig. 3) by means of which it 100 may be turned for adjusting the position of the mote board. The mote board proper has a plate 220 connected thereto, such plate being spaced from and substantially parallel with the under surface of the core 255 105 and connected to the latter in any desired manner, for example by flanges at its opposite ends. The plate 220 slides upon the upper face of rail 212 and is furnished with a down turned forwardly concave flange 221 110 at its front edge. The rear edge of plate 220 may be rolled or headed over as shown at 222 if desired. The space between the plate 220 and the under side of the mote board proper provides an air passage leading 115 into the lower part of the moting space as hereinafter described.

An upwardly and rearwardly inclined partition 262 extends from the upper surface of the mote board toward the rear of 120 the front unit of the machine and merges into the bottom wall 263 of a flue structure within the rear unit of the machine and which is disposed immediately below the cover 12 of such rear unit. Preferably the 125 partition 262 as well as the wall 263 is lined with sheet metal.

An adjustable lip board 265 (Fig. 7) is

secured to a shaft 266 located at a point substantially in the vertical tangent plane of the rear of the brush cylinder. This shaft is journaled at its opposite ends in the end members 1 and 2 of the frame and, projecting beyond one of said members, is provided with an arm 267 (Fig. 3) having a segmental slotted portion 268 which may be adjusted by means of a set screw 269.

10 The lip board preferably consists of a core member of wedge section carrying a sheet metal cover 270 which extends upwardly from the lower edge of the core in diverging directions one portion overlapping the forward edge to the cover 12 of the rear unit and the other portion thereof extending peripherally around the brush and beneath the rear edge 271 of the cover 4 of the front unit. As thus constructed the adjustment of 15 the lip board does not interfere with the proper flow of the air current passing up through the flue 264 nor does it permit leakage of air outwardly between the front and rear units of the machine.

20 25 A cross rail 272, preferably of channel iron, extends between the end members 1 and 2 beneath the forward edge of the member 263. A rear wall member 273 extends downwardly from the rail 272, being mounted 30 upon brackets 274 secured to the under surface of the partition 262. The lower edge of the member 273 is spaced vertically from the plate 220 to provide a passage through 35 which air may enter beneath the mote board 255.

A shaft 275 is journaled in the brackets 274 and projects beyond one of the end frames where it is provided with a slotted segmental arm 276 (Fig. 3) by means of 40 which it may be adjusted and secured in position.

The shaft 275 carries arms 277 to whose rear ends links 278 are pivotally connected. The lower ends of these links are attached to 45 a damper 279 hinged to the lower edge of a damper 279 hinged to the lower edge of the wall member 273. This damper is thus adapted to control the entrance passage leading to the space 280 between the mote board and the plate 220.

50 Dust separator.

The preferred form of dust separating device herein chosen for illustration comprises a cylindrical chamber 281 (Fig. 8) in the upper rear portion of the rear unit of the machine. The flue 264 terminates in this chamber 281, entering the latter through a peripheral opening, one edge of which is defined by the end 284 of the partition 263. 55 From the point 284 a curved extension 283 of the partition 263 continues downwardly to form a portion of the wall of the chamber 281. The upper part of the partition 263 as well as the curved extension 283 thereof is supported upon brackets 285 carried by

rods 286 whose opposite ends are secured to the end frames 9 and 10 of the rear unit.

The rear edge of the entrance passage between the flue 264 and the chamber 281 is defined by a partition 287, preferably of sheet metal, secured at its upper end to a rearwardly inclined continuation 288 of the cover 12 of the rear unit. This member 287 is supported upon brackets 288^a attached to the member 288, such brackets also being supported by rods 289 and 290 secured in the end frame members 9 and 10. The lower edge of the member 287 is secured to an angle bar 291 carried by the brackets 288^a, and from this bar a cylindrically curved screen 292 of foraminous material extends downwardly and forwardly and has its lower edge secured to an angle bar 293 also carried by the brackets 288^a. The screen 293 forms a portion of the cylindrical wall of the member 288 and from the point 293 this wall is continued by means of a sheet metal plate 294, one edge of which is secured to the top of a wall member 295 extending upwardly from the upper part 296 of the rear wall 13 of the rear unit. The plate 294 extends forwardly and then downwardly and has its forward edge 297 supported upon a shaft 354 hereinafter described. The edge 297 of the plate 294 is spaced from the lower edge 298 of the part 283 to provide an outlet passage 299 for the dust-separating chamber.

From the lower edge 298 of the wall member 283 a partition 300, preferably of circular curvature, extends forwardly until it merges with the partition 263 at the point 301.

A shaft 302 is journaled within the dust separator chamber 281 and this shaft carries a cylinder 303, preferably of wood, supporting a helically extending series of brush arms 304. If desired the cylinder may be omitted, the arms being secured directly to the shaft. These arms are preferably of tubular construction, and each arm supports a brush tuft 305 at its outer end. The arms 304 with their brush tufts are of such a length as to cause the brush tufts to contact with the inner surface of parts 283, and 294 and with the inner surface of the screen 292 as the shaft 302 is rotated, and the arms are so spaced along the shaft that all parts of the screen are swept by them and thus kept free from accumulation of lint.

The shaft 302 is mounted in suitable bearings 306 (Fig. 4) carried by the end frame members of the rear unit, and is provided at one end with a pulley 302^a (Fig. 3) driven by a crossed belt 302^b receiving its motion from the pulley 185 hereinbefore described upon the doffer brush shaft.

An enclosed dust bin 307 is provided at the rear of the screen 292. This dust bin comprises a movable cover 308 hinged at 309 to the member 288, a vertical rear wall 310,

and a floor 311, the latter preferably being of sheet metal and of trough-shape.

An endless screw conveyor 312 mounted upon a shaft 313 is arranged in the bottom of the trough-like floor 311. The shaft 313 is mounted in suitable bearings in the end frames and is provided at one end with a drive sprocket 314. At its opposite end the shaft 313 with its conveyor projects into a housing 315 (Figs. 2 and 14) which covers an opening in the end frame 10 concentric with the axis of the shaft 313. This housing is provided with ears 316 by means of which it is secured to the end frame and comprises an upper substantially circular chamber 317 concentric with the conveyor and a lower substantially circular chamber 318. The housing is open at its bottom at 319 to provide a dust discharge orifice.

20 A shaft 320 extends axially of the chamber 318, being journaled in bearing in the walls of the housing, and being furnished with a drum 321 carrying a series of circumferentially spaced resilient blades 322. These blades are of such a length that they drag against the inner walls of the chamber 318, so that they form a seal to prevent free entrance of air through the orifice 319. The conveyor shaft 313 is provided with a gear 323 (Fig. 2) which meshes with a gear 324 on the shaft 320.

Settling chamber and condenser.

From the point 301 (Fig. 8) the cylindrically curved wall 300 is extended downwardly and rearwardly as indicated at 325, this portion of the wall being supported upon brackets 326, carried by rods 327 secured at their opposite ends in the frame members 9 and 10. The wall 325 terminates at the point 325^a and from this point a second cylindrically curved wall 329 extends, the lower portion of this wall being bent downwardly and terminating substantially at the point 330 spaced vertically from the floor 11 of the rear unit. This wall is supported upon brackets 328.

Brackets 331 are secured at the rear wall member 13 of the rear unit and these brackets support a cylindrically curved wall 332 whose forward edge is bent downwardly and terminates at 333, leaving a lint delivery orifice 334 of elongate form between it and the terminus 330 of the wall 329.

55 The condenser drum shaft 335 is mounted concentrically with the walls 329 and 332, bearings 336 (Fig. 13) being provided for supporting this shaft.

At points adjacent to the bearings 336 the end walls 9 and 10 are provided with outwardly offset portions 337, in which bearings 336 are mounted and providing chambers 338 adjacent to the opposite ends of the shaft 335.

The shaft 335 supports the condenser 65 drum C comprising a pair of fixed spiders 339 having rims 340 disposed substantially in the vertical planes of the inner surfaces of the main portions of the walls 9 and 10 respectively. Each of the rims 340 (Figs. 70 29 and 30) is furnished with a series of circumferentially spaced radial slots for the reception of bars 340^a connecting the rims. These bars are furnished with notches in their outer edges for positioning a spirally wound wire 341 which embraces the bars tightly and which supports a cylindrical screen 342. Screen 342 fits snugly over the wire 341 and its end portions are bent or flanged inwardly as indicated at 343, 80 Fig. 30, such ends being clamped securely against the ends of the bars 340^a by means of clamping rings 344.

These rings 344 are secured to the rims 340 by means of screws 345 and are furnished 85 with portions 346 which project radially beyond the peripheral surface of the screen 342. These projecting portions or flanges 346 contact with flaps 347 of flexible material secured to the end walls 9 and 10 respectively of the rear unit. These flaps contact with the flanges 346 and provide a substantially air-tight joint between the ends of the drum and the main portions of the end walls 9 and 10. The ends of this cylinder are open to the chambers 338 and the latter communicate freely with the space 90 447 (Fig. 11) within the casing immediately below the condenser drum.

To prevent leakage of air between the periphery of the drum C and the wall members 325 and 329 a flexible flap or sealing member 348 (Fig. 8) is secured to the lower part of the wall 325. This flap extends longitudinally from one side wall of the casing 100 105 to the other and has its free edge in contact with the peripheral surface of the drum.

The shaft 335 of the condenser cylinder or drum C is provided with a gear 349 at one end, see Fig. 3, which meshes with a pinion 110 350 (Fig. 2) turning upon a stub shaft 351 secured to the end frame 9. This pinion is fixedly secured to a gear 352 which meshes with a pinion 353 upon the shaft 354, above mentioned, extending transversely across the machine and which is provided with a pulley 355 (Fig. 4) at its opposite end. This pulley is driven by means of a crossed belt 356 which engages a pulley 357 upon the shaft 28, above described.

115 The shaft 354 is provided with a second pulley which drives a belt 358 engaging the pulley 216, above described upon the shaft 215 of the mote conveyor 214. An idler pulley 359 may be employed for securing proper 120 125 contact of the belt 358 with its driving pulley.

The shaft 354 is also provided with a

sprocket 360 (Fig. 3) driving a chain 361 which passes about the sprocket wheel 314 upon the dust collector conveyor shaft 313.

Bat doffing mechanism.

5 The rear wall of the rear unit is provided with a transverse opening whose upper edge is defined by a rail 362 secured to the lower edge of the member 296. The 10 lower edge of the opening is defined by a curved member 363 which may form a continuation of the wall 332.

Brackets 363^a and 364^a (Figs. 3, 4 and 8) 15 are secured to the rear edges of the end frames 9 and 10 respectively. These brackets support bearings for a presser roll shaft 364, and for a doffer roll shaft 365. At one end the shaft 364 is provided with a pinion 366 (Fig. 2) which meshes with a pinion 367 20 upon the shaft 365. The shaft 364 is also provided with a pinion 368 which meshes with the gear 349 above described. The shaft 365 thus turns in substantially the same direction as the condenser shaft 335, 25 while the presser roll shaft 364 turns in the opposite direction.

The presser roll shaft 364 carries a cylindrical roll 369 preferably of wood or similar material, and a flexible flap 370 seals the 30 joint between the peripheral surface of this roll and the lower edge of the member 296.

The shaft 365 carries a cylindrical roll 371 provided with longitudinally extending slots in its peripheral surface. These slots 35 are preferably non-radial, being disposed in secant relation to the periphery of the cylinder. Within the slots resilient strips 372, preferably of rubber or similar material, are seated. The edges of these strips project 40 beyond the periphery of the cylinder to a distance sufficient to cause them to contact with the inner surface of the member 363 as the shaft 365 rotates and also to contact with the peripheral surface of the condenser 45 cylinder. The contact of these strips with the member 363 prevents the passage of air beneath the doffer roll while the passage of air beneath the doffer roll and the presser roll is prevented by means of a housing 373 50 secured to the outer edge of the member 362 and depending across the face of the presser roll and terminating in an outwardly directed flange 374 with which the strips 372 contact.

55 A shaft 375 is journalled at its opposite ends in the lower parts of the brackets 363^a and 364^a, and carries a lap roll 376. This roll is preferably formed of foraminous material and is of such a diameter that its peripheral surface is spaced slightly from the periphery of the doffer roll. To prevent 60 passage of air or other material between the rear surface of the lap roll and the doffer roll the number 363 may be provided with a 65 depending flange 332^a extending to a greater

or less extent about the peripheral surface of the lap roll.

The shaft 375 is provided at one end with a sprocket wheel 377 (Fig. 3) driven by means of a chain 378 engaging a sprocket 70 379 (Fig. 2) mounted upon the shaft 365. The lap roll thus turns in the same direction as the doffer roll 371.

Arms 380 and 381 are pivotally secured as 75 by means of stub shafts 382 to the brackets 363^a and 364^a respectively. These arms extend downwardly and are provided with hooks 383 at their lower ends. These hooks provide open bearings for the reception of the opposite ends respectively of a shaft 384 80 carrying a bat roll 385. This bat roll preferably consists of a solid wooden cylinder upon which the bat of fibre is rolled up as it is formed, and receives its motion by frictional contact with the surface of the lap roll 376.

The rear unit of the machine is preferably provided with glazed openings 387 and 388 in one of its end walls, and the front unit of 90 the machine may likewise be provided with glazed openings 389. Preferably also, the

walls of the casing are furnished with openings for the reception of removable sprinkler head supports 389^a carrying sprinkler heads of any usual type, automatic or otherwise, and connected to a suitable water supply. The rear unit, and if desired the front unit, is provided with openings in the wall opposite that having the aforesaid glazed 95 openings, and these latter openings are closed by means of casings 390 and 391 (Fig. 4) which support electric lamps such as 392 (Fig. 8) at suitable points within the casing. If the lamps are not employed, it is preferred to substitute therefor one or more 100 glazed openings, in the wall of the casing, opposite to the first mentioned openings so as to permit light from the exterior to enter from both sides.

The openings together with the lamps in 110 the casing permit ready inspection of the operations going on within the casing, and greatly facilitate proper adjustment of the various instrumentalities so as to secure the most efficient operation.

Float roll drive.

The shaft section 93 of the float roll is provided as above described with a gear 96 (Fig. 10). This gear meshes with a gear 120 394 journalled in a casing 395 and maintained constantly in mesh with the gear 96 by means of a casing 396 concentric with the shaft 93 and having a portion 397 which partially embraces the casing 395, being free 125 to turn upon the latter.

The casing 395 is secured by means of a bracket 398 to a collar 399 concentric with and free to turn in a casing 399^a concentric 130 with a shaft 400 suitably supported upon the

end frame 2 of the main or front section of the machine. This shaft 400 carries a gear 412 which is driven as hereinafter described.

Drive unit.

In accordance with the preferred construction the main drive shafts of the machine are carried upon a separate frame which may be placed against the end of the machine proper to transmit the power to its several instrumentalities. Such a drive unit may readily be made to accommodate a machine upon either side thereof, or may be made to drive but a single machine. In the construction herein selected for illustration the drive unit is intended to drive but a single machine.

The drive unit has a base comprising a foot 402 and transverse rails 403 and 404 respectively whose ends may be bolted to the end frame 2 of the machine proper. Transversely spaced standards 405 and 405^a rise from this base structure, being held in parallel relation by means of transverse rods or bars.

The upper surfaces of the uprights 405 and 405^a are furnished with seats 406 for bearings 407 and 408 respectively in which a main drive shaft 409 is journaled. A drive pulley 410 is mounted upon the shaft 409 intermediate the standards 405 and 405^a. A pinion 411 is also secured to the shaft 409 adjacent to the pulley 410. This pinion meshes with a gear 412 carried by the shaft 400, above described. The gear 412 and the pinion 411 are preferably enclosed within a housing 414 which preferably provides a bearing for the outer end of shaft 400. The shaft 400 also carries a pulley 415 for driving the belt 30.

The left-hand end of the drive shaft 409, as viewed in Fig. 1, is provided with a fixed clutch element 416 (Fig. 28). A sleeve 417 is arranged to slide longitudinally upon the clutch element 416. The clutch member 416 is furnished with a flange at its outer end provided with circumferentially spaced teeth 418. These teeth are preferably rounded in contour and engage corresponding longitudinal slots or recesses 419 in the inner face of the sleeve 417. The sleeve 417 may thus slide longitudinally but is constrained to rotate with the clutch element 416.

To lock the sleeve 417 against accidental longitudinal movement it is provided with a locking lever 420 (Fig. 27) pivotally mounted upon a pin 421 carried by the sleeve 417 and seated within a radial slot 422 in the latter member. A spring 423 is disposed below the end 420^a of the lever 420 while the opposite end of the lever is connected by a pin-and-slot connection to a locking latch or pin 424, sliding in a radial bore in the sleeve 417 and cooperating with

a recess 425 in the peripheral surface of the clutch member 416.

This locking lever with its pin 424 thus normally prevents longitudinal movement of the sleeve 417 relatively to the clutch member 416, but by depressing its end 420^a 70 in opposition to the spring 423 the lever may be actuated to release the pin 424 from the recess 425, thus allowing the sleeve to be retracted.

The shaft 174 of the saw cylinder is provided at one end with a fixed clutch element 426 having teeth 427 similar to the teeth 418 of the clutch element 416. The shaft 174 substantially aligns with the shaft 409 when the saw cylinder is in operative position and 80 the sleeve 417 is of sufficient length to embrace the toothed portion of the member 426 whereby to clutch the shafts 409 and 174 together.

Preferably the teeth 418 do not fit the recesses 419 tightly so that a slight degree of transverse relative movement is permitted between the shafts 409 and 174. Such freedom of movement is desirable as it avoids the necessity of aligning the shafts with absolute accuracy each time the saw cylinder is withdrawn and replaced.

The upper surfaces of the standards 405 and 406 are also furnished with seats 428 (Fig. 5) for bearings 429 of which but one 95 is shown. These bearings support a drive shaft 429^a which is aligned with the shaft 183 of the doffer brush cylinder, and the adjacent ends of the shafts 429^a and 183 are furnished with disengageable clutch elements in all respects similar to those just described for uniting the shafts 409 and 174.

The shaft 429^a is furnished with a pulley 430 disposed intermediate the standards 405 and 405^a and in the plane of the drive pulley 105 410 above described.

The rear surfaces of the standards 405 and 405^a are provided with guideways 431 in which a supporting frame 432 is mounted to slide vertically. This frame is provided 110 with bearings in which a shaft 433 is journaled. This shaft carries a belt-tightening pulley 434 disposed in the same plane as the pulleys 410 and 430.

The inner or front face of the frame 432 115 is provided with spaced vertical racks 435 and 436 (Fig. 6) meshing respectively with pinions 437 and 438 carried by a shaft 439 journaled at its opposite ends in the standards 405 and 405^a. This shaft is also provided with a worm wheel 440 meshing with a worm 441 mounted upon the rear end of a shaft 442 journaled in bearings 443 and 444 carried by the standard 405^a. A hand wheel 445 is mounted upon the forward end of the shaft 442. In one arrangement of overhead drive, a belt 446 extends downwardly and beneath the drive pulley 410, thence up-

wardly and over the pulley 430, and thence downwardly and beneath the pulley 434 and thence upwardly again to a drive pulley upon the power shaft, not shown. By turning the hand wheel 445 the belt-tightening pulley 434 may be moved up or down so as to tension the belt 446 against the pulleys 480 and 430. By this means the machine proper may be stopped or started when desired without disturbing the operation of other machines driven from the same power source.

While one arrangement of overhead drive is herein illustrated, the relation of drive and belt tightening pulleys is such as to permit various other arrangements of drive, both overhead and underneath, and it is to be understood that the exact mode of training the belt about the pulleys forms no essential feature of the invention.

The modified construction of breast structure support or back illustrated in Fig. 42 comprises a channel bar 520 having horizontally disposed forwardly extending upper and lower flanges. The brackets 54 and 55 are bolted to the upper part of the bar 520 and the forward edge of the lower flange is notched to receive the upper ends of the grate fall bars 109. A clamp bar 112 is bolted to the lower flange of the channel bar to retain the grate fall bars in position.

A guide or guides 710 is secured to the upper flange of the channel bar providing a bearing for the feeler shaft 72 and also supporting the upper edge of a forwardly concave sheet metal piece 711 forming the rear wall of the roll box. The lower part of the part 711 is secured to blocks 712 attached to the vertical web of the channel bar.

Preferably a strip 713 of flexible material for example canvas, is attached to the rear face of the vertical web of the channel bar by means of a bottom strip 714, and extends rearwardly and downwardly over the upper edge of the resilient flap 208 to seal the joint between the division board 198 and the breast structure. The lower edge of the canvas strip is preferably weighted by means of a rod 715.

Operation (Figs. 11 and 12).

The machine operates substantially as follows, it being understood that the belt 446 has been tensioned to drive the pulleys 410 and 430 and that the hopper or feed box 21 has been supplied with seed or other material to be operated upon. In the absence of material from the roll box 87 the feeler 60 73 drops forwardly and thus removes the shield 38 from beneath the pawl 35. As the shaft 28 is rotating continuously the pawl 35 turns the ratchet wheel 36 and thus rotates the feed roll 23. The seed or other material now feeds downwardly into the roll

box 87 where it is rotated slowly by the float roll within the box. When the roll of seed has reached a maximum diameter the feeler member 73 is lifted, thus placing the guard 38 beneath the pawl and causing the flow 70 of seed from the hopper temporarily to cease.

As the float roll turns it presses the roll of seed against the grate-fall bars 109 and thus permits the rotating saw blades 178 75 to tear the fibres from the seeds, the de-linted seeds sliding down beneath the rake head and being delivered through the seed guide casing 139.

The fibre carried by the saw blades passes 80 around to the line of osculation 452 of the saw cylinder with the doffer brush B where the fibre is brushed off from the saw teeth and thrown downwardly into the air current generated by the revolving brush. This air 85 current passes down along the rear wall of the draft board 223, and as it enters the moving space M an eddy current is set up which causes motes, trash, and other similar material to settle out into the bottom 90 of the trough 210.

The direction of the eddy is clockwise as viewed in Fig. 11. Were the draft shield provided with a smooth surface there might be a tendency for the motes, particularly 95 when the draft shield is set at a substantial angle to the vertical, to escape upwardly along the shield into the current delivered by the brush and to be swept thereby into the flue 264. This undesirable action is very 100 effectually prevented by roughening or corrugating the draft shield in the manner described. Apparently the upwardly moving motes contact with the irregularities of the draft shield and are thus stopped or it may 105 be that they enter the still air space existing between and adjacent to such irregularities of the draft shield and are thus arrested in their upward flight, but whatever the action that deprives them of their kinetic energy, 110 the result is that they settle out of the air current into the space below the mote board.

The lighter fibre remains suspended in the air current and is carried upwardly through the flue 264 and enters the dust 115 separator chamber 281 in a substantially tangential direction. As the fibre-carrying air current sweeps around against the screen 292 forming the rear wall of the dust separator chamber, the fine particles of dust, 120 sand, and very short fibre pass out through the screen into the dead air space in dust box 307 while the longer fibre emerges from the dust separator through the opening 299 into the space or settling chamber immediately above the condenser cylinder C. Any long fibre lodging against the screen 292 is brushed off by the brush on shaft 302 and returned to their air current.

The settling chamber is of relatively 130

large capacity as compared with the flue 264 so that the velocity of the air is greatly reduced and by reason of the shape of the chamber and eddy current tends to form. 5 These features cause the fibre to settle out of the air in an evenly distributed manner upon the peripheral surface of the rotating condenser cylinder C, the air current from which the fibre is thus separated passing 10 through the interstices of the cylinder and out through its opposite ends into the chambers 338 from whence it passes freely into the chamber 447 in the lower part of the rear unit. Any small amounts of lint tending 15 to collect between the lower part of the cylinder and the partitions 329 and 332 discharges through the orifice 334.

As the bat of fibre upon the condenser cylinder approaches the doffer roll 371, it 20 is separated from the condenser cylinder and caused to pass between the presser roll 369 and the doffer roll so as to be compressed into a self-sustaining sheet. This sheet or bat then moves out over the upper surface 25 of the lap roll 376 and is wrapped around the bat roll 385, the latter being driven by contact with the lap roll 376.

The long useful fibre is thus formed into a continuous bat upon the bat roll and may 30 be removed with said roll when a sufficient amount has been accumulated, a fresh roll then being placed in the bearings of the hooks, 383 to receive a further supply of fibre.

35 At the same time the short and dirty fibre deposited in the dust box 307 is discharged from the latter by means of the conveyor 312 through the rotating valve structure arranged in the housing 315.

40 The motes which accumulate in the trough-like member 210 are discharged from the hood 218 as above described.

The air which enters the chamber 447 passes forwardly into the rear portion 448 45 of the front unit of the machine and a part of this air is induced by the suction created by the doffer brush to enter the passage 280 beneath the mote board. This air assists materially in producing the desired eddy current at the left hand end of passage 280 as viewed in Fig. 11. The balance of the air which enters chamber 448 moves forwardly and up through the space 449 between the front wall of the front unit and 50 the trough 210. A portion of this air passes downwardly through the space 450 between the lower edge of the member 229 of the draft shield and the support 174 for the trough 210 and this air moves downward through the passage 254 at the lower end 55 of the draft shield, entering the moting space in a direction such as to cause it to impinge upon the concave flange 221 which further assists in setting up an eddy current in the moting space.

Another portion of the air passing up through the passage 449 moves between the member 229 of the draft shield and the periphery of the saw and thus assists in cleaning the fibre from the saw blades and 70 prevents such fibre from moving forwardly with the saw blades where it could escape the moting action. This cleaning current augmented by a small quantity of air which passes up beneath the seed guide casing and 75 enters the machine casing between the lower edge of rail 117 and the upper end of the seed board 146. This space permits sufficient air to enter to compensate for air which may be discharged from the casing 80 with the clean fibre and motes, or which may otherwise escape, and also furnishes a vent to take care of air expansion due to temperature changes, as well as more violent 85 expansions, such for example as dust explosions within the casing.

As the entire casing is enclosed the same current of air is used continuously and there is substantially no discharge of lint or fly into the work room. At the same time the 90 gin structure is of self-contained character and may be set up without references to other machines and without necessitating the employment of long lines of piping 95 or other conduits leading to a common condensing apparatus. Each machine delivers the clean fibre in the form of a bat or roll which is convenient for handling while it also separates the dirty and short fibres from the longer and clean fibre, delivering 100 such dirty fibre at another point.

If in the operation of the machine it becomes necessary to replace the saw cylinder, the breast structure may be lifted by means of handles 151 and 166 and after 105 disengagement of the clutch elements 417 and 427 and release of the retaining hooks 176, the hand wheel 175 may be manipulated to swing the brackets S forwardly from out the casing, thus moving the saw cylinder 110 shaft bodily forward and permitting its bearings with the shaft to be removed as a unit from the machine without difficulty and without substantially disturbing the other parts of the structure. A fresh saw 115 cylinder may now be mounted upon the brackets S and may be moved into operative position by manipulation of the hand wheel 175.

The brush cylinder B may likewise 120 be removed from the front of the machine after removal of the saw cylinder without substantially disturbing the other parts of the machine so that if the brush cylinder becomes worn its replacement may easily 125 be accomplished.

As all of the operative instrumentalities are adjustable from the outside of the machine and as such adjustment may be visually controlled by observation through the 130

glazed openings in the casing, great accuracy of operation is attainable and a much more uniform product is secured.

While certain specific arrangements have hereinbefore been described for supporting and adjusting the various operative instrumentalities and for driving the latter, it is understood that the invention is not limited in its broader aspects to the specific arrangements disclosed, but that other and equivalent means may be employed, as circumstances may make desirable, without departing from the spirit of the invention.

I claim:

1. A gin having a substantially closed casing in which a fibre conveying air current circulates, means for separating useful fibre from seeds and for delivering the separated fibre into the air current, and means for separating the clean lint from the air current and for delivering such clean lint in the form of a continuous bat directly from the casing, the air current freed from lint returning within the casing to fibre receiving position.

2. A gin comprising a substantially closed casing having therein means for separating useful fibre from its attachments and delivering such fibre into an air current, a condenser for such fibre, mechanical means for stripping the fibre from the condenser and delivering it outside the casing, and means for directing the air current freed from fibre back to fibre receiving position.

3. A gin comprising a substantially closed casing having therein means for separating useful fibre from its attachments and delivering such fibre into an air current, a rotary condenser for separating the fibre from the air current, and means for stripping the condensed fibre in the form of a continuous sheet from the condenser, air current freed from lint at the condenser returning to fibre receiving position.

4. A gin comprising a casing, means therein for separating useful fibres from their attachments, means for doffing the separating means and for throwing the separated fibre into an air current moving in the casing, means within the casing for moting the fibre, for condensing the clean fibre into a bat, and for returning the air stripped of fibre by the condensing means to receive further fibre.

5. A gin comprising a closed casing having therein a rotary saw cylinder, a doffer brush cooperable therewith, means defining a moting space below the line of osculation of the saw cylinder brush, means for condensing the cleaned fibre, means for guiding a fibre bearing air current from the moting space to the condenser means, said condensing means delivering the fibre in the form of a bat from the casing, and means for guiding the air current freed from fibre at the

condensing means back to the moting space.

6. A gin comprising a closed casing, a rotary saw cylinder therein, mechanical means for doffing fibre from the saw cylinder and delivering it into an air current, a dust separator, means directing the fibre conveying air current to the separator, a condenser for removing clean fibre from the air current, means for stripping the fibre from the condenser and delivering it outside the casing, and means guiding the air current freed from fibre back to the fibre receiving point.

7. A gin comprising a closed casing, a rotary saw cylinder therein, means for presenting fibrous material thereto, a doffer brush having its axis in substantially the same horizontal plane as that of the saw cylinder, the brush producing a fibre conveying air current, means defining a moting space below the line of osculation of the brush and saw, a flue leading upwardly from the moting space, means for condensing fibre and for delivering it in the form of a bat from the casing, and means for returning the air, freed from fibre, to receive a further supply of fibre.

8. A gin comprising a casing enclosing a saw cylinder and doffer brush, a breast structure, means supporting the breast structure to swing upwardly from operative to inoperative position and also for bodily adjustment, and means for sealing the joint between the hinge edge of the breast structure and the casing when the breast structure is in operative position.

9. A gin having a breast structure comprising a roll box and grate fall, a bracket rigidly secured to the breast structure, said bracket being pivotally supported to swing about a substantially horizontal axis, an arm rigidly secured to the bracket, and a counterpoise supported by said arm.

10. A gin having a breast structure comprising a roll box and grate fall, means supporting the breast structure to turn about an axis to the rear of the roll box, an arm rigidly secured to the breast structure and normally extending upwardly and rearwardly, and a counterpoise supported by the arm.

11. A gin having a breast structure, means supporting the breast structure to swing about a substantially horizontal axis, a pair of parallel rigid arms projecting from the breast structure, a bar connecting the free ends of the arms, and a plurality of removable weights mounted upon the bar for counterbalancing the breast structure.

12. A gin having a breast structure comprising spaced end members and a back, the latter defining the rear wall of a roll box, spaced brackets rigidly secured to the back, said brackets being pivotally supported to permit the breast structure to turn about a horizontal axis, a rigid arm projecting

rearwardly from each bracket, and a counterpoise supported by said arms for counterbalancing the weight of the breast structure.

13. A gin having a breast structure pivoted to swing from operative to inoperative position, and a pair of manually actuatable devices operable respectively to move the breast structure to different degrees away from its operative position and positively to 10 retain it in each of its adjusted positions.

14. A gin having a saw cylinder, a pivotally supported breast structure, a rigid arm projecting rearwardly from the breast structure, and a bell crank lever, one arm thereof 15 constituting a handle and the other arm thereof having a part overlying said rigid arm, movement of the bell crank lever depressing said rigid arm and thereby lifting the breast structure to inoperative position.

20. 15. A gin having a saw cylinder, a grate fall comprising spaced bars between which the saws of the cylinder are positioned and above which they normally project, manually operable means for raising the grate fall 25 just enough to clear the peripheries of the saws from between the bars and for temporarily retaining it in such position, and a hand lever for further lifting the breast structure to a position such as to permit 30 removal of the saw cylinder.

16. A gin having a saw cylinder, a breast structure comprising a grate fall normally cooperating with the cylinder, means for moving the breast structure to a position 35 such that the grate fall no longer cooperates with the saw cylinder, and independent means for further moving the breast structure to a position such as to permit removal of the saw cylinder and for retaining it in 40 the latter position.

17. A gin having a breast structure, means pivotally supporting the breast structure to turn about a substantially horizontal axis, a rigid arm secured at one end to the breast structure and having a counterweight 45 mounted upon its opposite end, and a manually operable lever having an anti-friction roll engageable with said rigid arm at a point intermediate the ends of the latter, said roll moving bodily in an arcuate path when the lever is swung thereby to depress 50 said arm and lift the breast structure to inoperative position.

18. A gin having a breast structure pivoted to turn about a substantially horizontal axis, an arm rigidly connected at one end to said breast structure, a shaft provided with a crank having a crank pin engaging said arm at a point intermediate its ends, and means for rocking the shaft whereby to 55 move the crank pin and thereby to turn the breast to inoperative position, said crank pin in its movement passing from one side to the other of the vertical plane of the axis

of the crank thereby positively holding the 60 breast structure in inoperative position.

19. A gin having a breast structure pivoted to turn about a substantially horizontal axis, an arm rigidly secured to the breast structure, a shaft provided with a crank 70 having an antifriction roll engaging the arm, a lever for rocking the shaft whereby to swing the arm and turn the breast structure to inoperative position, and a stop for limiting movement of the lever. 75

20. A gin having a breast structure pivoted to turn about a substantially horizontal axis, a pair of arms projecting from the breast structure substantially at right angles to the axis about which it turns, a pair of 80 shafts each having a crank, the respective cranks each being provided with a crank pin engaging one of the respective arms, said crank pins engaging the arms at different distances from the axis of the breast structure, and means for turning the shafts. 85

21. A gin having a breast structure pivoted to turn about a substantially horizontal axis, an arm projecting from the breast structure substantially at right angles to the axis about which the latter turns, a shaft 90 extending transversely of the arm, a crank secured to the shaft having a crank pin engageable with the arm, and a lever movable through a limited arc for turning the shaft 95 to swing the crank pin through an arc intersecting the plane defined by the axis of the shaft and the pivotal axis of the breast structure whereby to move the breast structure to inoperative position and to retain it 100 in said position.

22. A gin having a frame, a breast structure pivotally mounted in the frame to swing upwardly from its operative position, arms rigidly secured to the breast structure adjacent to its opposite ends, said arms normally projecting upwardly and rearwardly, a shaft journaled in either end of the frame, said shafts being parallel to the axis about which the breast structure turns and at different 110 distances from said axis, a crank secured to each shaft, the cranks having pins overlying the respective arms and engageable with the latter, and a lever for turning each shaft, the parts being so constructed and arranged 115 that when either lever is swung to its maximum extent the corresponding crank pin is moved to depress its corresponding arm and to retain said arm in depressed position. 120

23. A closed circuit gin comprising a substantially closed casing having chambers and passages providing an endless path for air currents, said casing enclosing a saw cylinder and means for producing a fiber sustaining air current, a brush structure pivoted to swing forwardly and upwardly, said breast structure having a back, and a strip of flexible material for sealing the joint between 125

the back of the breast structure and the casing.

24. A gin having a saw cylinder support, a breast structure pivoted to swing upwardly from operative to inoperative position, and means for adjusting the breast structure bodily in a vertical direction to accommodate saws of different diameters.

25. A gin comprising a saw cylinder support, a breast structure, and means for adjusting the breast structure vertically to accommodate saw cylinders of different diameters.

26. A gin having a saw cylinder support, a breast structure comprising a grate fall and rake-head, a pivotal support about which the breast structure may swing upwardly to inoperative position to clear the saw cylinder, and means for adjusting the pivotal support bodily in a vertical direction to change the position of the breast structure to accommodate saws of different diameters.

27. A gin having a saw cylinder support, a breast structure provided with a journal opening, a supporting shaft extending through said journal opening and defining a pivotal axis about which the breast structure may swing, and means for adjusting the shaft vertically to accommodate the breast structure to saw cylinders of different diameters.

28. A gin having a breast structure provided with a journal opening, a shaft for supporting the breast structure extending through the opening, guideways for the opposite ends of the shaft, the shaft having parallel, internally threaded diametral openings adjacent to its opposite ends respectively, and set screws engaging the respective openings for adjusting the shaft in its guideways.

29. A gin having a breast structure provided with bearing brackets having aligned journal openings, a shaft for supporting the breast structure extending through said openings, the shaft having parallel vertical surfaces at its opposite end portions, vertical guideways for receiving and guiding said end portions of the shaft, and set screws for adjustably positioning the shaft in said guideways.

30. A gin having a breast structure comprising spaced end members, a back uniting the end members and constituting the rear wall of a roll box, and a breast board forming the front wall of the roll box, said breast board having pins near its upper edge at its opposite ends removably seated in notches in the respective end members and releasable in the respective end members and releasable in the respective end members and releasable in the respective end members.

31. A gin having a breast structure comprising a back, means pivotally supporting the breast structure to swing upwardly to

inoperative position about a horizontal axis, and a breast board constituting the front wall of the roll box, said breast board normally moving with the remainder of the breast structure but being detachable therefrom.

32. A gin having a breast structure comprising a back and spaced end members, a grate fall, and a breast board constituting the front wall of a roll box, said breast board comprising spaced end frames disposed adjacent respectively to said end members, each frame having a pin removably seated in an open notch in the adjacent end member, means rigidly connecting the end frames, and a forwardly convex cover connecting said frames, and having its lower edge spaced from the grate fall.

33. A gin having a breast structure comprising spaced end members and a back member, the latter constituting the rear wall of a roll box, a grate fall secured to the back and extending downwardly and forwardly therefrom, and a breast board constituting the front wall of the roll box, said breast board comprising spaced end frames and a forwardly convex sheet metal cover connecting said frames, a pin projecting from each end frame, said pins being removably seated respectively in open notches in the respective end frames, and retractable bolts normally connecting the lower part of the breast board to the respective end members.

34. A gin comprising a float roll, means for supporting the float roll to permit bodily adjustment thereof, and means operable in all positions of the roll for rotating the roll.

35. A gin comprising a float roll, means supporting the float roll to move bodily in a predetermined path to and from operative position, and drive means operative in all positions of the roll for driving it.

36. A gin comprising a float roll, means supporting the float roll to permit rectilinear adjustment and also movement thereof in an arcuate path, and means, operative in all positions of the roll, for rotating it.

37. A gin comprising a saw cylinder, a float roll, means for adjusting the float roll bodily toward and from the saw cylinder, and a gear train comprising constantly meshing gears for driving the float roll in all positions of adjustment.

38. A gin having a breast structure comprising a float roll, means for adjusting the breast structure vertically and for moving it in an arcuate path to and from operative position, and a train of constantly meshing gears operative to turn the float roll in all positions of the breast structure.

39. A gin having means for supporting a saw cylinder and a grate fall cooperating with the saw cylinder comprising a series of spaced, parallel independent bars of hardened steel, each bar being of substantially

uniform rectangular cross section from end to end.

40. A gin having a saw cylinder and a grate fall cooperating therewith, the grate fall comprising a series of parallel hardened steel bars of substantially uniform transverse section from end to end, metallic supporting rails engaging the bars of the series at their upper and lower ends respectively, 10 and an elongate metallic clamping member common to all of the bars for securing all of the bars to at least one of the rails.
41. A gin having a saw cylinder and a grate fall, the latter comprising a series of independent rectangular bars of substantially uniform cross section from end to end, spaced supporting rails extending longitudinally of the series of bars, an abutment member carried by one rail, one end of each bar resting against the abutment, and a single elongate clamp member associated with the other rail having a wedge surface engageable with the opposite end of each bar to force the latter firmly against the abutment member.

42. A gin having a saw cylinder and a grate fall cooperating therewith, said grate fall comprising a series of independent bars of uniform rectangular cross section, and means common to all of the series and engaging the bars of the series at their front and rear ends respectively for clamping and supporting them in spaced relationship.

43. A gin having a saw cylinder and a grate fall cooperating therewith, said grate fall comprising front and rear supporting rails, a single elongate clamping member detachably secured to each of said rails, and a plurality of grate bars having their opposite ends removably secured to the respective rails by the clamping members.

44. A gin having a saw cylinder and a grate fall cooperating therewith, the grate fall comprising a supporting rail, a series of parallel bars, and a removable clamping member for securing said bars to the rail, said clamping member being provided with spacing members for holding the ends of the several bars in spaced relation.

45. A gin having a saw cylinder and a grate fall, the latter comprising an elongate supporting rail, parallel bars each having one end supported upon the rail, and a removable clamp plate common to the several bars securing said ends of the bars to the rail, said plate having spaced slots for the reception of the ends of the several bars.

46. A gin having a saw cylinder and a grate fall, the latter comprising a series of spaced bars each having one end bevelled, means for supporting the opposite ends of the several bars in fixed position, a rail underlying the bevelled ends of the bars, and an elongate plate having an undercut bevelled face engageable with the bevelled

ends of all of the bars of the series to clamp said bevelled ends securely against the underlying rail.

47. A gin having a breast structure comprising spaced end members, a grate fall, 70 a breast board supported by the end members, the lower edge of the breast board being spaced from the grate fall, a rake head comprising an elongate bar provided with downwardly projecting teeth, a plurality of spaced screw threaded rods connected to the bar, nut members engaging the respective threaded rods, an actuating element, and gearing for transmitting movement from the actuating element to the several nut members for simultaneously turning the latter.

48. A gin having a breast board comprising spaced end members, a rail connecting said members, a grate fall, a rake head, 85 spaced brackets mounted upon the rail, a shaft journaled in said brackets, a hand wheel for turning the shaft, spaced pinions secured to the shaft, a peripherally toothed nut mounted in each of the brackets and meshing with the respective pinions, means restraining the nuts against axial movement, a screw threaded rod engaging each nut, and means connecting the rods to the rake head.

49. A gin having a breast board comprising spaced end members, a grate fall, a rake head comprising an elongate bar provided with a series of teeth, screw threaded rods pivotally secured to the bar 100 at spaced points, a supporting rail connecting the spaced end members, a rotary shaft carried by said rail, pinions secured to the shaft, and peripherally toothed nut members meshing with the respective pinions and engaging the threaded rods whereby upon rotation of the shaft the rake head is raised and lowered.

50. A gin having a breast structure comprising a rearwardly concave breast board, 110 spaced end supports therefor, a bottom rail connecting the end supports, a seed guide comprising spaced end plates, a curved shield secured to the end plates having its upper edge normally engaging said bottom rail, and hooks for detachably securing said end plates to the respective end supports.

51. A gin having a breast structure having spaced end members and a forwardly 120 and downwardly inclined grate fall, a breast board having its lower edge spaced from the grate fall, a downwardly directed guide shield arranged to direct the seeds downwardly as they are delivered from the 125 lower end of the grate fall, a pin projecting from each of the end members and means suspending the guide shield from said pins, the suspending means being freely removable from the pins.

52. A gin having a breast structure comprising a pivotally supported back and end members secured thereto, a breast board detachably connected to said end members, 5 and a seed guide detachably connected with the breast board.
53. A gin having a breast structure comprising a forwardly inclined grate fall, a breast board, a rake-head, movable relatively 10 to the breast board, and a cover member movable with the rake-head and spaced from the lower part of the grate fall to provide an enclosed passage for the discharge of the seeds.
54. A condenser gin having a substantially closed casing in which air is moved in a closed circuit, said gin having a breast structure comprising an inclined grate fall, a breast board having its lower edge spaced 20 from the grate fall, a rake-head adjustable toward and from the grate fall, a guide shield for directing the seeds delivered from the grate fall in a predetermined path, the upper edge of the guide shield normally 25 being spaced from the rake-head, and a sealing plate hinged at its front and rear edges respectively to the guide shield and to the rake-head.
55. A condenser gin having a substantially 30 closed casing in which air is moving in a closed circuit, said gin having a breast structure comprising a movable back constituting the rear wall of a roll box, a breast board constituting the front wall of the roll box, 35 a rake-head on the lower edge of the breast board adjustable relatively to the latter, the breast board and rake-head being detachable as a unit, and a detachable seed guide for determining the path of seeds escaping 40 beneath the rakehead.
56. A gin having a breast structure comprising a breast board, spaced end supports therefor, each support being provided with a projecting pin, a grate fall spaced from the 45 lower edge of the breast board, and a seed guide comprising a downwardly curved shield having its upper edge spaced above the lower part of the grate fall, and end plates supporting the shield, each of said plates 50 having a hook member detachably engageable with the respective pins of the end supports.
57. A condenser gin having a substantially 55 closed casing in which air is caused to circulate in a closed path, said gin having a breast structure comprising a breast board, spaced end members supporting the breast board, a bottom rail connecting the end members, a grate fall spaced from the 60 lower edge of the breast board, a rake head spaced from the bottom rail and adjustable toward and from the grate fall, a seed guide shield normally engaging said bottom rail, and flexible sealing means connecting the 65 bottom rail and rake-head and constituting in effect a continuation of the shield intermediate the bottom rail and rake-head.
58. A gin having a breast structure comprising a breast board, spaced end supports for the board, a bottom rail connecting the 70 end supports, said rail being spaced from the lower edge of the breast board, an adjustable rake-head adjacent to the lower edge of the breast board, a downwardly curved seed guide shield supported by said 75 end supports and having its upper edge normally engaging the bottom rail, and a sealing plate hingedly connected both to the bottom rail and rake head.
59. A gin having a casing provided with 80 end walls and a front wall, a saw cylinder mounted within the casing, an inclined seed board extending upwardly from the upper edge of the front wall of the casing substantially to the periphery of the saw cylinder, and end members supporting the seed board, said end members being detachably secured respectively to the opposite end walls of the casing.
60. A gin having a casing provided with 85 a front wall and spaced end walls, a saw cylinder having its periphery spaced from the upper edge of said front wall, and a forwardly and downwardly inclined seed board 90 extending from the front wall substantially to the periphery of the saw cylinder, members supporting the seed board, said seed board being detachably secured respectively to the opposite end walls of the casing to 95 permit withdrawal of the saw cylinder from the casing.
61. A gin comprising a casing, a saw cylinder normally positioned therein, bearings for the saw cylinder, a breast structure, 100 means for moving the breast structure to anoperative position, and means for moving the saw cylinder bearings bodily forward out of the casing when the breast structure has been moved to inoperative position.
62. A gin comprising a casing, aligned 105 saw cylinder bearings, and means for moving said bearings for supporting the cylinder during operation of the gin with the saw cylinder mounted therein from a position 110 inside the casing to a position outside the casing.
63. A gin comprising a saw cylinder, a bearing for each end of the cylinder, said 115 bearings supporting the cylinder during 120 operation of the gin, means supporting each bearing to move in an arcuate path about a fixed center, and means for swinging said supporting means simultaneously and to the same degree to carry the saw cylinder from 125 operative to inoperative position.
64. A gin having a saw cylinder provided with a shaft and means for supporting it in 130 operative position in the gin comprising a pair of spaced sector-like brackets pivoted to rock about the same axis, a bearing car-

ried by each bracket for the reception respectively of the opposite ends of the saw cylinder shaft, said shaft turning in said bearings when the gin is operating, and means for rocking the brackets simultaneously.

65. A gin having a saw cylinder and means for supporting it comprising a pair of spaced brackets pivoted to rock about a common axis, bearings carried by the respective brackets for supporting the opposite ends of the saw cylinder, a curved rack mounted upon each bracket, said racks being curved concentrically with the axis about which the brackets rock, a shaft provided with pinions engaging the respective racks, and means for turning the shaft.

66. A gin comprising a casing, a saw cylinder, a cylinder supporting bracket pivoted to rock about a fixed axis adjacent to its lower end, a bearing carried by said bracket for supporting the saw cylinder during operation of the gin, said bracket having an elongate arcuate opening therein, and a member engaging said opening to limit movement of the bracket with the saw cylinder outwardly from the casing.

67. A gin having a saw cylinder, a pair of spaced brackets pivoted to swing about a common axis adjacent to their lower ends, supports carried by the respective brackets for the opposite ends of the saw cylinder, each bracket having an arcuate opening concentric with its pivotal axis, a shaft extending through the openings in the respective brackets, pinions upon the shaft, an arcuate rack upon the inner edge of each opening engaging one of the respective pinions and means for turning the shaft.

68. A gin comprising a casing, a saw cylinder, a pair of spaced cylinder supporting brackets pivoted to rock about a common axis adjacent to the bottom of the casing, said brackets having arcuate openings therein, a shaft journaled in the casing and extending through the openings in the respective brackets, pinions carried by the shaft engaging racks carried by the respective brackets, means for turning the shaft, and a hook carried by each bracket engageable with the shaft to retain the brackets in normal position with the saw cylinder within the casing.

69. A gin comprising a casing, a saw cylinder, a movable support for the saw cylinder, and releasable latch means for retaining the support in normal position with the saw cylinder within the casing.

70. A gin comprising a casing, a saw cylinder, a rocking support for the saw cylinder, and a hook member for retaining the support in normal position with the saw cylinder within the casing.

71. A gin comprising a casing, a saw cylinder, a cylinder supporting bracket pivoted to rock about an axis adjacent to the bottom

of the casing, a hook carried by the bracket, and a relatively fixed member carried by the casing with which the hook engages to hold the bracket in normal position with the saw cylinder within the casing.

72. A gin comprising a casing, a drive shaft, bearings normally supporting a saw cylinder shaft in line with the drive shaft, a disengageable coupling for connecting the saw cylinder shaft with the drive shaft, and means for moving the saw cylinder shaft 75 bearings after disengagement of the coupling to carry the cylinder forwardly out of the casing.

73. A gin comprising a movable support 80 provided with bearings for a saw cylinder shaft, a drive shaft, coupling means for connecting the saw cylinder shaft and drive shaft in one position of the cylinder shaft supporting means whereby to turn the cylinder shaft in its bearings, said coupling means comprising mating parts axially movable to disengage them and also capable, when engaging, of slight relative movement to compensate for inaccuracy of alignment 85 of their respective shafts, and means actuatable, after disengagement of the coupling means, to move the cylinder shaft supporting means to carry the cylinder out of alignment with the drive shaft.

74. A gin comprising a casing having a breast structure at its front, said casing having end walls each provided with a recess extending rearwardly from its front edge, a removable bearing normally disposed within each recess, said bearing supporting the opposite ends respectively of a doffer brush shaft, and a doffer brush carried by said shaft, the breast structure being movable upwardly to expose the brush cylinder for removal with its bearings from the front of the casing.

75. A gin comprising a normally closed casing having end walls each provided with a recess extending inwardly from its front edge, two pairs of removable bearings normally disposed in said recess, a doffer brush shaft journaled in one pair of said bearings, a brush mounted on said shaft, and a saw cylinder having a shaft journaled in the other pair of bearings, the casing having a portion of its front wall pivoted to move upwardly whereby to permit removal of both sets of bearings from the recesses.

76. A gin comprising a casing having end walls each provided with a recess extending inwardly from its front edge, means for removably supporting a doffer brush shaft bearing adjacent to the inner end of each recess, a brush shaft journaled in said bearings, and a removable closure plate normally filling the forward portions of said recesses in front of said bearings.

77. A gin comprising a rotary saw cylinder, a rotary doffer brush, a division

board projecting into the angle between the peripheral surfaces of the saw cylinder and brush respectively, and means for moving the division board bodily in a direction substantially parallel to the plane defined by the axes of the saw cylinder and brush.

78. A gin comprising a rotary saw cylinder, a rotary doffer brush, the axes of the brush and cylinder lying substantially in the same horizontal plane, a division board projecting into the angle between the peripheral surfaces of the brush and saw cylinder, respectively, and supporting means for the board arranged to permit its movement in a horizontal direction.

79. A gin comprising a casing having therein a rotating saw cylinder, a doffer brush cylinder rotating oppositely to the saw cylinder, parallel guideways at opposite ends of the casing, a support slidably engaging each guideway, a division board having its opposite ends secured to the respective supports, and means disposed outside the casing for adjustably positioning the respective supports relatively to their guideways.

80. A gin having a closed casing provided with an adjustable breast structure, a saw cylinder, a doffer brush, a division board having a bevelled lower edge projecting downwardly into the angle between the peripheral surfaces of the cylinder and brush, and flexible means interposed between the division board and a portion of the breast structure to seal the joint between said parts in all adjusted positions of the breast structure.

81. A gin comprising a closed casing, a rotary saw cylinder, a doffer brush rotating oppositely to the saw cylinder and arranged to create an air current moving in a closed circuit in the casing, a draft shield extending downwardly from a point closely adjacent to the periphery of the brush, and means for directing a portion of the air current between the saw cylinder and the upper edge of the draft shield, and for directing another portion of the air current beneath the shield.

82. A gin comprising a closed casing, a rotary saw cylinder therein, means for doffing fibre from the saw cylinder and throwing it into a current of air flowing in a closed circuit in the casing, a draft shield extending downwardly from the saw cylinder, means for dividing the current of air and causing portions thereof to flow past the upper and lower edges of the draft shield respectively, and means for varying the relative amounts of air flowing past the upper and lower edges of the shield.

83. A gin having a casing in which a fibre conveying air current circulates, a trough-like partition spaced from the bottom of the casing and constituting the bottom wall

of a moting space, a draft shield constituting one side wall of the moting space and having its lower edge spaced from said partition, and a mote board at the other side of said space having a passage beneath it, a portion of the air current flowing through said passage into the moting space and another portion flowing below the partition and then down below the lower edge of the draft shield into the moting space.

84. A gin comprising a saw cylinder, a draft shield pivotally supported adjacent to the periphery of the saw cylinder, and means for swinging the draft shield about its pivotal support.

85. A gin having a saw cylinder and a draft shield cooperating therewith, the draft shield being supported adjacent to its upper edge to swing about an axis adjacent to the periphery of the saw, a shaft having a crank arm, a link connecting the crank arm with the lower part of the draft shield, and means for turning the shaft and securing it in adjusted position.

86. A gin comprising a casing having therein a rotating saw cylinder and a doffer brush, a draft shield, and means for optionally adjusting either the upper or lower edge of said shield without substantially disturbing the other edge thereof.

87. A gin comprising a saw cylinder, a draft shield, means for supporting the draft shield to swing about an axis adjacent to the periphery of the saw cylinder, and means for adjusting the position of said supporting means.

88. A gin comprising a saw cylinder, a draft shield, means for supporting the draft shield to swing about an axis adjacent to the periphery of the saw cylinder, and means for adjusting said supporting means in a plurality of directions.

89. A gin having a saw cylinder and a draft shield, the draft shield being pivoted to swing about its upper edge as an axis and being bodily adjustable to maintain said edge closely adjacent to the periphery of the saw cylinder irrespective of the diameter of the latter.

90. A gin having a saw cylinder, a draft shield, and means providing a pivotal support for the draft shield comprising a fulcrum member adjustable in a direction substantially tangent to the periphery of the saw cylinder.

91. A gin having a saw cylinder, a draft shield, and a knife edge fulcrum for the draft shield, said fulcrum being adjustable in a path substantially tangent to the periphery of the cylinder and also in a direction transverse of said path.

92. A gin having a saw cylinder and a draft shield, the latter comprising spaced end frames, a piece of sheet material connecting the end frames, an adjustable ful-

crum engaging a bearing surface adjacent to each end respectively of the draft shield to support the latter, and means for adjusting said fulcrums simultaneously.

93. A gin having a saw cylinder, a draft shield and means for supporting the draft shield comprising an adjustably slidable block and a fulcrum member adjustably mounted upon the block.

94. A gin having a saw cylinder, a draft shield, and means for supporting the draft shield comprising a slide block, guide means therefor, a threaded rod secured to the slide block, a nut engaging the rod for retaining it with the block in selected position of adjustment, and a fulcrum member for the draft shield mounted upon the block.

95. A gin having a saw cylinder, a draft shield, and means for supporting the draft shield comprising a block guided to slide toward and from the periphery of the saw cylinder, means for adjusting said block and for retaining it in selected position of adjustment, a shaft journalled in the block, a lever arm fixed to the shaft, said lever arm having an arcuate slot therein, a locking bolt passing through said slot and engaging a threaded opening in the block, a second arm secured to the shaft, a link pivoted to the latter arm, said link having an elongate slot, a guide pin projecting from the block into the slot, and a fulcrum at the free end of the link forming a pivotal support for the draft shield.

96. A gin having means for separating useful fibres from their attachments, means for doffing the separating means and for creating a fibre conveying air current moving in a closed circuit, means for removing useful fibre from the current, and means for dividing said current after removal of the fibre therefrom and for causing divisions thereof to flow in intersecting paths to produce a moting eddy.

97. A gin having means for separating useful fibres from their attachments, means for throwing the separated fibres into a closed circuit of air, means for separating useful fibre from the air current, means providing a moting space, and means for dividing the air current after removal of the fibre therefrom and for delivering divisions of said current into the moting space in directions such as to induce the formation of an eddy in such space.

98. A gin comprising means for separating useful fibres from their attachments, means for doffing the separating means and for throwing the fibres into an air current moving in a closed circuit, means defining a moting space, and means for delivering regulable portions of said air current into different parts of said moting space.

99. A gin having a casing in which a cur-

rent of air circulates in a closed path, said casing having a moting space, means directing a portion of the air current into the lower part of the moting space, and means for directing a regulable portion of such current into the upper part of the moting space.

100. A gin comprising a substantially closed casing, means for creating a circulating air current within the casing, said current being adapted to carry fibre while making a portion of its circuit, said casing having a moting space, means for delivering a portion of said air current into said space adjacent to the upper part of the latter, and means for delivering a regulable part of said air current into the lower part of said space.

101. A gin having a casing in which a current of air circulates, means defining a moting space comprising a substantially horizontal mote board, and a passage beneath the mote board for admitting a portion of the air current to the moting space.

102. A gin having a casing in which a current of air circulates, means defining a moting space, said means comprising a substantially horizontal mote board having an air passage immediately below it, and means for adjusting the mote board horizontally.

103. A gin having a casing in which a fibre conveying air current circulates, means defining a moting space, said means comprising a horizontally positioned mote board having a passage beneath it, and a movable damper for controlling the quantity of air moving through said passage.

104. A gin having a casing in which a fibre conveying air current circulates, means defining a moting space, said means comprising a mote board having horizontal members spaced vertically to provide an air passage leading into the moting space, a pivoted damper for controlling the movement of air through said passage, and means for adjusting the damper.

105. A gin having a casing in which a fibre conveying air current circulates, means defining a moting space, said means comprising a substantially vertical draft shield, an adjustable, horizontal mote board, passages below both draft shield and mote board opening at opposite sides of the moting space, means for adjusting the draft shield to vary the size of the passage beneath it, a damper for controlling the passage beneath the mote board, and means for adjusting the positions of the mote board and damper.

106. A gin comprising a closed casing having a saw cylinder and doffer brush rotating therein, the casing having a moting space at its lower part, a partition defining one wall of the moting space, a mote board mounted to slide in a plane intersecting the

- plane of the partition, there being an air passage immediately below the mote board leading to the moting space, and means for adjustably positioning the mote board.
- 5 107. A gin comprising a closed casing in which air moves in a closed circuit, said casing having therein a saw cylinder and a doffer brush, the axes of the brush and cylinder being in substantially the same horizontal plane, a draft shield extending downwardly in a substantially vertical direction from below the saw cylinder, a horizontal mote board beneath the brush, there being a passage immediately beneath the mote board through which a portion of the circulating air passes, and means for adjusting the mote board to move one of its edges toward and from the face of the draft shield.
- 10 108. A gin comprising a closed casing in which air moves in a closed circuit, said casing having therein a saw cylinder and a doffer brush cylinder rotating in opposite directions upon shafts disposed in a substantially horizontal plane, a draft shield extending downwardly from a point adjacent to the periphery of the saw cylinder and constituting one wall of a moting space, a mote board guided to slide horizontally toward and from the draft shield, there being a passage below the mote board leading to the moting space, said mote board being provided with a rack, a pinion engaging the rack, a shaft supporting the pinion, and a hand wheel upon the shaft outside the casing for turning the shaft.
- 15 109. A gin comprising a casing having a saw cylinder journaled therein, means for inducing a stream of air within the casing, and means for retarding the movement of the air carried particles at one side of said stream without substantially deflecting the stream from its original course.
- 20 110. A gin comprising a saw cylinder and doffing means, and means defining a moting space, in which an air current moves, said means comprising a part having a roughened surface to retard the movement of motes carried by the air current without substantially changing the direction of the air current as a whole.
- 25 111. A gin comprising a casing, and partitions therein defining a moting space through which a current of air flows, one of said partitions being substantially straight and having a surface provided with ribs extending transversely of the normal path of the air current.
- 30 112. A gin comprising a saw cylinder, a rotary doffer brush delivering a current of air in a downward direction substantially tangent to the periphery of the saw cylinder, and a substantially straight draft shield extending downwardly from a point adjacent to the periphery of the saw cylinder, said
- 35 draft shield having a corrugated surface exposed to said current of air.
- 40 113. A gin comprising a saw cylinder and a doffer brush, the latter being constructed and arranged to deliver a current of air, and a draft shield terminating at a point closely adjacent to the periphery of the saw cylinder, said draft shield constituting one wall of a moting space and having a roughened surface.
- 45 114. A gin having a closed casing in which a current of air circulates, a saw cylinder and doffer brush in the upper part of the casing, a trough-like partition spaced from the lower part of the partition, a horizontal mote board beneath the brush and extending over the trough, a partition extending rearwardly and upwardly from the mote board forming the bottom wall of a flue leading to a condenser, the air from the condenser returning to a point below the trough-like partition, means permitting a part of said air to escape beneath the mote board, and other portions of the air passing forwardly and up over the front edge of the trough-like partition.
- 50 115. A gin comprising a closed casing having means therein for separating fibres from their attachments and for throwing said fibres into an air current circulating in the casing, a trough-like member defining the bottom wall of a moting space, a conveyor disposed in said trough-like member arranged to move motes collecting therein toward the wall of the casing, said casing having an opening in its wall for the delivery of the motes, and a discharge hood projecting from the outer side of said wall concentric with said opening, said hood having a normally closed movable cover.
- 55 116. A gin having a casing in which a lint conveying air current circulates, means for supplying lint to the air current, means for removing dust from the lint laden air current, a condenser for removing clean lint from the air current, and means for directing the air current, freed from lint, back to the lint supplying means.
- 60 117. A gin having a casing in which a lint conveying air current circulates, means supplying lint to the air current, means for producing a moting eddy in the air current to cause motes and trash to settle out, means for removing dust from the lint laden air current, a condenser for separating clean lint from the air current, and means for directing the air current, substantially freed from lint, back toward the lint supplying means.
- 65 118. A gin having means for separating useful fibre from its attachments, means for doffing said separating means and for throwing the fibre into a moving air current, means for subjecting the suspended fibre to a moting operation, means for di-

- recting the air current with its mated fibre to a dust separator, means for directing the air current to a condenser, and means for directing the air current, substantially freed from lint, back to the separating and doffing means. 119. A gin having a casing in which a lint conveying air current circulates, a foraminous partition within the casing having a dead air space at one side, means directing the lint laden air current to flow in contact with the opposite side of the partition, and means for disengaging lint deposited upon said partition from the surface thereof. 120. A gin having a casing in which a lint conveying air current circulates, said casing comprising a dust box, a screen forming an inner wall of the box, means directing the lint laden air current to pass over the outer face of the screen, and means for brushing collected fibre from the screen. 121. A gin having a closed casing in which a fibre conveying air current circulates and means for separating dust from the air current comprising a substantially cylindrical chamber into which the air current is admitted in a substantially secant direction, that part of the chamber wall against which the air impinges being foraminous, and a rotary brush for removing fibre from said foraminous wall. 122. A gin having a casing in which a fibre conveying air current flows, said casing having an upwardly directed flue for the air current, a dust removing chamber at the terminus of said flue having an opening adjacent to its top for admitting the air current, a curved foraminous wall in said chamber arranged to deflect downwardly the moving current of entering air and to deliver it substantially horizontally, and means for brushing off fibres deposited at substantially any part of the foraminous wall. 123. A gin having a casing in which a fibre conveying air current flows, and means for separating dust from the air current comprising a substantially cylindrical chamber, a portion of the cylindrical wall of said chamber being of foraminous material, a rotating shaft disposed axially of said chamber, a helically arranged series of brush tufts carried by the shaft, the brush tufts engaging the foraminous wall of the chamber as the shaft rotates, the wall of the chamber having an opening extending longitudinally thereof to admit the air current to enter in a secant direction to impinge against the foraminous portion of the wall, and a second opening for the discharge of the air current. 124. A gin having a closed casing in which a fibre conveying air current circulates, means for separating dust from the air current, a rotary spiral conveyor for moving the separated dust toward a delivery opening in the wall of the casing, a housing covering said opening, said housing having a downwardly open discharge orifice, a rotary valve within the housing obstructing the free passage of air through the latter, and means for continuously rotating the valve. 125. A gin having a closed casing in which an air current circulates, means for separating suspended dust from the air current, a spiral conveyor for moving the separated dust toward a discharge opening in the wall of the casing, a housing covering said discharge opening, and a constantly rotating valve within the housing constructed and arranged to permit the dust to pass out while opposing the free passage of air. 126. A gin comprising a casing provided with a substantially horizontal support at its opposite ends, a movable doffer brush bearing mounted upon each support, a doffer brush shaft journaled in said bearings, a drive shaft normally aligned with the brush shaft and mounted in fixedly supported bearings, and a clutch coupling normally connecting the drive shaft and brush shaft, said clutch coupling having disengageable parts to permit the shafts to be disconnected for removal of the brush shaft from the casing. 127. A gin comprising a casing provided with a movable front closure, a doffer brush cylinder within the casing, said cylinder having a shaft, a drive shaft normally aligned with the brush shaft and turning in fixed bearings, and disengageable clutch means for connecting the drive shaft and brush cylinder shaft, the brush cylinder being removable through the front of the casing after disengagement of the clutch means and movement of the front closure of the casing to inoperative position. 128. A gin comprising a casing, a breast structure forming a portion of the front wall of the casing, a saw shaft and a doffer brush shaft normally supported in removable bearings within the casing, a pair of oppositely rotating drive shafts normally aligned with the saw shaft and brush shaft respectively, and disengageable clutches connecting the saw shaft and brush shaft to the respective drive shafts, the breast structure being movable to permit removal of the saw shaft and brush shaft from the casing after disengagement of the clutches. 129. A gin having a rotating saw shaft, bodily movable bearings therefor, a drive shaft, and cooperating disengageable clutch elements carried by the respective shafts, said clutch elements being constructed and arranged to transmit power to the saw shaft.

- even though the shafts are not exactly aligned, and means for moving the bearings to carry the saw shaft forwardly out of operative position.
130. A gin comprising a casing having a support at either end, a bearing normally resting upon each support, a doffer brush shaft mounted in said bearings, a clutch element secured to one end of the shaft, and a drive shaft normally aligned with the saw shaft and brush shaft respectively, having a clutch element complementary to the clutch element upon the brush shaft and engageable therewith to connect the shafts.
131. A gin having a rotary doffer brush shaft and a shaft for driving the brush shaft, and complementary disengageable coupling elements carried by the respective shafts, said elements being capable of relative radial motion to compensate for minor errors in alignment of said shafts.
132. A gin comprising a casing, saw and doffer brush shafts journaled in removable bearings in the casing, a pair of drive shafts mounted in fixed bearings outside of the casing, and means for releasably clutching the saw and brush shafts to the respective drive shafts.
133. A gin having a saw cylinder shaft, a rotary doffer brush shaft, a clutch element secured to each shaft, drive shafts aligned with the saw and brush shafts respectively, and a clutch element slidably keyed to each drive shaft and engageable respectively with the clutch elements of the saw and brush shafts for driving the latter.
134. A gin having a casing, a saw cylinder shaft and a doffer brush shaft mounted therein, a frame disposed adjacent to one end of the casing outside the latter, a pair of drive shafts journaled in the frame, said shafts being independent of the cylinder and brush shafts, a pulley upon each drive shaft and disengageable means for coupling the respective drive shafts to the saw and brush shafts, respectively.
135. A gin having fibre separating and condensing means, and a drive unit comprising a frame adapted to be set adjacent to one end of the gin proper, said frame supporting a pair of drive shafts journaled therein, said drive shafts being independent of the shafts of the fibre separating and condensing means, a pulley fast to each shaft, a bodily removable idler pulley for tighten-
- ing a belt engaging the drive pulley, and means for transmitting motion from the drive shafts to the fibre separating and condensing means.
136. A gin having a saw shaft, and a brush shaft, and a drive unit disposed at one end of the gin proper, said unit comprising a frame, a pair of parallel drive shafts journaled therein, said shaft being substantially aligned respectively with the saw and brush shafts, a pulley fast to each shaft, a vertically movable slide, an idler pulley carried thereby, means for adjusting the slide whereby to tension a driving belt passing over the drive and idler pulleys, and disengageable means for coupling the drive shafts to the saw and brush shafts respectively.
137. A gin having a drive unit comprising a frame arranged at one end of the gin proper, a pair of shafts journaled in the frame, a drive pulley fast to each shaft, a vertically movable slide carried by the frame, an idler pulley mounted on the slide, a drive belt engaging the drive pulleys and the idler pulley, a rack carried by the slide, an adjusting shaft journaled in the frame having a pinion engaging the rack, a worm wheel upon the adjusting shaft, a shaft provided with a worm engaging said worm wheel, and means for turning the latter shaft.
138. A gin comprising a substantially air tight casing enclosing instrumentalities for separating useful fibre from its attachments, for throwing said fibre into an air current, and for condensing the fibre, certain of said instrumentalities having adjustable parts, means outside the casing for adjusting said parts during operation, said casing having a glazed opening in one of its walls, a removable support covering an opening in its opposite wall, and an electric lamp mounted upon the support inside the casing.
139. A gin having a closed casing, means therein for separating useful fibres from their attachments and for cleaning such fibres, said casing having an opening in its wall, a removable cover normally closing the opening, and a sprinkler head mounted upon the inner side of said cover.

Signed by me at Boston, Massachusetts this 1st day of August, 1924.

ROBERT W. McLEAN.
